Associated Electric Laboratories, Inc., Chi-
cago, Ill., a corporation of Delaware

Application November 18, 1940, Serial No. 366,127

24 Claims. (Cl. 179—27)

The present invention relates to telephone systems and more particularly to improved automatic switching apparatus of the character of that disclosed and claimed in U. S. Patent No. 2,070,874, John H. Voss and Thomas F. Crocker, granted February 16, 1937, which apparatus is connected and arranged to handle switchboard traffic.

A telephone system of the character of that disclosed in the Voss and Crocker patent mentioned comprises a switchboard provided with a number of operator positions and a number of groups of switching links individually associated with the operator positions, each operator position comprising equipment operative to select for use any idle one of the switching links in the associated group. Each switching link includes an answer switch and a call switch, the answer switch of a selected switching link being operative to select a calling toll or trunk line accessible thereto and the call switch of a selected switching link being operative to select a called toll or trunk line accessible thereto. The operation of the answer switch of a selected switching link is controlled automatically by a distributor commonly associated with the groups of switching links; while the operation of the call switch of a selected switching link is under the control of the position equipment at the associated operator position.

In a telephone system of this character, the operator at an operator position at the switchboard frequently disconnects a switching link in use from the associated operator position after the operation of the call switch thereof has been controlled and prior to the complete operation of the call switch, particularly when the switching link is utilized to extend a connection to a local subscriber substation. This mode of operation of the equipment at the operator position in conjunction with the extension of connections to local subscriber substations is employed in view of the fact that the connections are routed by way of a local switch train, in which automatic ringing of the called subscriber substations is utilized.

While this mode of operation of the equipment at the operator position is very advantageous in that it appreciably facilitates rapid extension of calls to local subscriber substations, it does not permit of complete supervision of the completion of such connections. For example, when this mode of operation of the equipment at the operator position is employed and the called local subscriber substation is found to be

busy incident to the complete operation of the local switch train, the busy tone signal returned from the local switch train over the switching link in use to the calling line is not transmitted to the associated operator position, the switching link in use being disconnected from the associated operator position at this time. Hence, the operator at the associated operator position is not advised of the noncompletion of the connection due to the busy condition mentioned.

Accordingly, it is an object of the present invention to provide in a telephone system of the character described, including an operator position and a link selectively connectable thereto, an improved arrangement for supervising connections extended over the link, regardless of whether the link is connected to or disconnected from the operator position.

Another object of the invention is to provide in a telephone system, including an operator position and an associated switching link operative to extend connections therefrom, an improved arrangement for selectively controlling the operation of the switching link and for supervising connections extended thereover.

A further object of the invention is to provide in a telephone system, including an operator position, an improved switching link associated with the operator position which embodies simple and positive control and supervisory facilities.

The invention is illustrated as being embodied in a telephone system comprising a central office of any suitable type, a private automatic branch exchange or P. A. B. X., an intermediate branch exchange or I. B. X. of the automatic type and a distant exchange of any suitable type. A switchboard is arranged in the P. A. B. X. which comprises a number of operator positions. Further, a toll switch train is arranged in the P. A. B. X. which comprises a number of groups of switching links individually associated with the operator positions, each switching link including an answer switch and a call switch, the toll switch train being utilized to complete toll and trunk connections. Finally, a local switch train is arranged in the P. A. B. X., the local switch train being utilized to complete local connections in the P. A. B. X.

In accordance with one feature of the invention, the telephone system comprises a plurality of lines, an operator position, a link, means selectively controllable from the operator position for connecting the link to and for disconnecting the link from the operator position, means for connecting the link to a calling one of the lines,

and means for connecting the link to a called one of the lines. Also, the telephone system comprises means responsive to the connection of the link to a busy called line for impressing a busy signal upon the link, whereby the busy signal impressed upon the link is transmitted to the calling line connected to the link and also to the operator position in the event the link is connected to the operator position, a signal device associated with the operator position, and means responsive to the presence of the busy signal upon the link and governed only in the event the link is disconnected from the operator position for controlling the signal device.

In accordance with another feature of the invention, the link includes a voice current channel; and the busy signal is impressed by way of a high impedance path upon the channel of the link. Further, a tone detecting and amplifying arrangement is provided, which comprises an electric discharge device, including a space current path and a control electrode, means controlled in accordance with the resistance of the space current path for controlling the signal device, and means for amplifying the busy signal impressed upon the channel of the link and for impressing the amplified busy signal upon the control electrode, thereby to control the resistance of the space current path.

In accordance with a further feature of the invention, the telephone system comprises, in addition to the means responsive to the connection of the link to a busy called line for controlling the signal device, means responsive to the connection of the link to an idle called line and governed only in the event the call on the idle called line is not answered within a predetermined time interval after the link is connected thereto for controlling the signal device.

In accordance with a further feature of the invention, the telephone system comprises a timer, first and second intermittent signal voltages having different periodicities, means responsive to the connection of the link to a called line for operating the timer and for impressing either the first signal voltage or the second signal voltage upon the link, depending upon the idle or busy condition of the called line, apparatus operative through a complete cycle to control the signal device, means governed jointly by the presence of either one of the signal voltages upon the link and the operation of the timer for initiating operation of the apparatus, and means governed by the operation of the timer for arresting operation of the apparatus, whereby the apparatus is operated through a complete cycle of operation only in the event a predetermined one of the signal voltages is impressed upon the link. Further, an arrangement is provided for preventing operation of the timer, in the event the link is not disconnected from the associated operator position or in the event the link is connected to a called line of a particular class. Finally, the operation of the timer is arrested in the event the link is connected to an idle called line, when the call on the idle called line is answered.

Further features of the invention pertain to the particular arrangement of the circuit elements of the system, whereby the above-outlined and additional operating features are attained.

The novel features believed to be characteristic of the invention are set forth with particularity in the appended claims. The invention, both as to its organization and method of op-

eration, together with further objects and advantages thereof, will best be understood by reference to the following specification taken in connection with the accompanying drawings, in which Figure 1 illustrates the general arrangement of a telephone system embodying the present invention; and Figs. 2 to 6, inclusive, taken together, and arranged in side-by-side relationship, illustrate the details of a system having incorporated therein the features of the invention, as briefly outlined above.

Description of the apparatus incorporated in the telephone system

Referring now more particularly to Fig. 1 of the drawings, the telephone system there illustrated comprises a central office 20, a P. A. B. X. 30, an I. B. X. 40 and a distant exchange 50. The central office 20 and the distant exchange 50 are of any well-known type each serving a number of subscriber substations, not shown; while the P. A. B. X. 30 and the I. B. X. 40 are of the automatic type each serving a number of automatic subscriber substations. More particularly, the P. A. B. X. 30 serves a number of subscriber substations, including the subscriber substations T3 and T4; while the I. B. X. 40 serves a number of subscriber substations, including the subscriber substations T1 and T2. The central office 20 and the P. A. B. X. 30 are interconnected by a group of one-way trunk lines, including the trunk line 203 extending from the central office 20 to the P. A. B. X. 30, and a group of one-way trunk lines, including the trunk line 202 extending from the P. A. B. X. 30 to the central office 20. The I. B. X. 40 and the P. A. B. X. 30 are interconnected by a group of two-way trunk lines, including the trunk line 220 extending therebetween; while the distant exchange 50 and the P. A. B. X. 30 are interconnected by a group of two-way toll lines, including the toll line 226 extending therebetween.

The central office 20, the I. B. X. 40 and the distant exchange 50 respectively comprise an operator position 201, an operator position 217 and a toll operator position 225; while the P. A. B. X. 30 comprises an automatic dial switchboard provided with a number of operator positions, including the first operator position 301. Each trunk line in the group extending from the central office 20 to the P. A. B. X. 30 terminates at the operator position 201 in the central office 20 and in a trunk circuit in the P. A. B. X. 30, the trunk line 203 terminating in the trunk circuit 205. Similarly, each trunk line in the group extending from the P. A. B. X. 30 to the central office 20 terminates in a repeater in the P. A. B. X. 30 and at the operator position 201 in the central office 20, the trunk line 202 terminating in the repeater 204. Also, each trunk line in the group extending between the I. B. X. 40 and the P. A. B. X. 30 terminates at the operator position 217 in the I. B. X. 40 and in a trunk circuit in the P. A. B. X. 30, the trunk line 220 terminating in the trunk circuit 221. Finally, each toll line in the group extending between the distant exchange 50 and the P. A. B. X. 30 terminates at the toll operator position 225 in the distant exchange 50 and in a toll line circuit in the P. A. B. X. 30, the toll line 226 terminating in the toll line circuit 227.

The I. B. X. 40 is provided with a switch train comprising a number of finder-connector links, including the finder-connector link 216. Also, a telephone line having a line circuit individually

associated therewith extends to each of the subscriber substations in the I. B. X. 40, the telephone lines 210 and 212 respectively extending to the subscriber substations T1 and T2 and having the line circuits 211 and 213 respectively associated therewith. Finally, a number of trunk circuits are provided in the I. B. X. 40 which are individually associated with trunks terminating at the operator position 217 in the I. B. X. 40, the trunk circuit 215 being individually associated with the trunk 214 terminating at the operator position 217. It is noted that each finder-connector link in the I. B. X. 40 has access to each telephone line therein and to each trunk terminating at the operator position 217.

The P. A. B. X. 30 is provided with a local switch train comprising a number of local finder-selector links, including the local finder-selector link 235, and a number of local connectors, including the local connector 236. Also, telephone lines having line circuits individually associated therewith extend to each subscriber substation in the P. A. B. X. 30, the telephone lines 232 and 230 respectively extending to the subscriber substations T3 and T4 and having the line circuits 233 and 231 respectively associated therewith. A number of trunk circuits, including the trunk circuit 241, is provided in the P. A. B. X. 30. It is noted that each of the local finder-selector links has access to each telephone line in the P. A. B. X. 30, to each local connector and to a number of trunks individually extending to the trunk circuits, including the trunk 240 individually extending to the trunk circuit 241; while each of the local connectors has access to each telephone line in the P. A. B. X. 30.

Further, the P. A. B. X. 30 is provided with a toll switch train comprising a number of groups of switching links individually associated with the operator positions at the switchboard, one of the groups, including the switching link illustrated, being individually associated with the first operator position 301 at the switchboard. Each of the switching links comprises a finder and a first selector, the switching link illustrated respectively comprising the finder 300 and the first selector 500. Also, it is noted that each of the switching links in the group, including the switching link illustrated, is commonly associated with the cable 302 extending to the first operator position 301. Also, the toll switch train comprises a group of toll connectors, including the toll connector 504; a group of second selectors, including the second selector 505; and a group of delayed call selectors, including the delayed call selector 570. Each switching link has individually associated therewith timer apparatus and tone apparatus, the timer apparatus and the tone apparatus individually associated with the switching link illustrated being respectively indicated at 510 and 600. Further, a distributor 250 is provided, which is commonly associated with the various operator positions at the switchboard and with the various trunk circuits and toll line circuits, for a purpose more fully explained hereinafter.

It is noted that each of the finders has access to a group of trunks individually extending to the group of trunk circuits, including the trunk circuit 205, this group including the trunk 207 individually extending to the trunk circuit 205; to a group of trunks individually extending to the group of trunk circuits, including the trunk circuit 221, this group including the trunk 222 individually extending to the trunk circuit 221;

5 to a group of trunks individually extending to the group of toll line circuits, this group including the trunk 223 individually extending to the toll line circuit 227; to a group of trunks individually extending to the group of trunk circuits, including the trunk circuit 241, this group including the trunk 243 individually extending to the trunk circuit 241; and to a group of trunks individually extending to the group of delayed call selectors, this group including the trunk 509 individually extending to the delayed call selector 570. Similarly, each of the first selectors and each of the delayed call selectors has access to a group of trunks individually extending to the group of toll connectors, this group including the trunk 502 individually extending to the toll connector 504; and to a group of trunks individually extending to the group of second selectors, this group including the trunk 503 individually extending to the second selector 505. Each of the toll connectors has access to a group of trunks individually extending to the group of repeaters, this group including the trunk 501 individually extending to the repeater 204; to a group of trunks individually extending to the group of trunk circuits, including the trunk circuit 221, this group including the trunk 506 individually extending to the trunk circuit 221; and to a group of trunks individually extending to the group of toll line circuits, this group including the trunk 507 individually extending to the toll line circuit 227. Finally, each of the second selectors has access to a group of trunks individually extending to the group of local connectors, this group including the trunk 508 individually extending to the local connector 236.

40 The operator position 201 in the central office 20, as best shown in Fig. 2, the operator position 217 in the I. B. X. 40, as best shown in Fig. 2, and the toll operator position 225 in the distant exchange 50, as best shown in Fig. 2, are connected and arranged in a conventional manner. Also, the subscriber substations T1 and T2 in the I. B. X. 40, as best shown in Fig. 2, and the subscriber substations T3 and T4 in the P. A. B. X. 30, as best shown in Fig. 2, comprise conventional substation equipment; while the line circuits and trunk circuits respectively associated with the telephone lines and the trunks in the I. B. X. 40, as best shown in Fig. 2, and the line circuits associated with the telephone lines in the P. A. B. X. 30, as best shown in Fig. 2, are connected and arranged in a conventional manner. Further, the finder-connector links in the I. B. X. 40, as best shown in Fig. 2, and the local finder-selector links and the local connectors in the P. A. B. X. 30, as best shown in Fig. 2, are connected and arranged in a conventional manner. Preferably, each of the finder-connector links comprises a finder and a connector of the well-known Strowger type; each of the local finder-selector links comprises a finder and a selector of the well-known Strowger type; and each of the local connectors is of the well-known Strowger type.

45 50 55 60 65 70 75 Preferably, each of the repeaters is identical to the repeater 204, shown in Fig. 2, which is connected and arranged in a conventional manner; each of the trunk circuits in the groups respectively including the trunk circuits 205, 221 and 241 is identical to the respective trunk circuits 205, 221 and 241, shown in Fig. 2, which trunk circuits 205, 221 and 241 are respectively connected and arranged in manners substantially

identical to the trunk circuits respectively shown in Figs. 4, 6 and 3 of the previously mentioned Voss and Crocker patent; and each of the toll line circuits is identical to the toll line circuit 227, shown in Fig. 2, which is connected and arranged in a manner substantially identical to the toll line circuit shown in Fig. 5 of the previously mentioned Voss and Crocker patent.

Preferably, the distributor 250, shown in Fig. 2, is connected and arranged in a manner substantially identical to the distributor shown in Fig. 20 of the previously mentioned Voss and Crocker patent; while each of the operator positions comprises apparatus identical to the first operator position 301, shown in Fig. 3, which first operator position 301 comprises operator position equipment including a position circuit, position relays, position control keys, a position calling device, position digit keys, a receiver, a transmitter, first and second sender links, and a number of digit register senders, and which operator position equipment is connected and arranged in a manner substantially identical to the operator position equipment shown in Fig. 21, part 1, part 2 and part 3, Fig. 22, part 1 and part 2, and Fig. 23 of the previously mentioned Voss and Crocker patent.

Preferably, each of the first selectors is identical to the first selector 500, shown in Fig. 5; each of the delayed call selectors is identical to the delayed call selector 570, shown in Fig. 5; each of the toll connectors is identical to the toll connector 504, shown in Fig. 5; and each of the second selectors is identical to the second selector 505, shown in Fig. 5; which first selector 500, delayed call selector 570, toll connector 504 and second selector 505 are respectively connected and arranged in a manner substantially identical to the first selector, the delayed call selector, the toll connector and the second selector, respectively, shown in Figs. 8, 9, 15 and 18 of the previously mentioned Voss and Crocker patent.

Preferably, each of the finders is identical to the finder 300, shown in Figs. 3 and 4, and comprises a switching mechanism 310 of the Strowger type, including a main wiper set provided with a number of wipers 311 to 316, inclusive, and capable of both vertical and rotary movements, and an associated main contact bank including ten vertical levels of contact sets arranged in circumferentially spaced-apart relationship. Also, the mechanism 310 includes a vertical control wiper 317 capable of vertical movement and an associated vertical control contact bank. The mechanism 310 is provided with a vertical magnet M320 for moving the wiper set thereof in the vertical direction, a rotary magnet M318 for moving the wiper set thereof in the rotary direction, and a release magnet M322 for releasing the wiper set thereof and for causing the wiper set to be returned to its normal position. Finally, the switching mechanism 310 has a number of sets of switch springs S323, S324 and S325 operatively associated therewith, which are controlled in accordance with the movements of the wiper set thereof, in a manner more fully described subsequently.

Further, the finder 300 comprises a group of relays including a cut-through relay R330, a transfer relay R340, a step relay R350, a start relay R360, a talk relay R370, a toll relay R400, three supervisory relays R410, R420 and R425, and a cut-in relay R430, connected and arranged in a manner more fully described subsequently. Moreover, the finder 300 has individually asso-

ciated therewith a link listening or talk key K380 and a monitor key K440 which are operative to associate the finder 300 with the cable 302 extending to the first operator position 301. Finally, a busy lamp L326, a supervisory lamp L327 and a hold lamp L409 are individually associated with the finder 300 for supervisory purposes.

Preferably, each of the timing apparatus is identical to the timing apparatus 510, shown in Fig. 5, which comprises a switch 511 of the minor type, including three wipers 512, 513 and 514 provided with individually associated contact banks. Also, the minor switch 511 comprises a rotary magnet M518 for driving the wipers noted in 15 the rotary direction and a release magnet M519 for releasing the wipers noted and for causing them to be returned to their normal positions. Finally, a set of switch springs S515 is associated with the minor switch 511 which is controlled in accordance with the movements of the wipers thereof, in a manner more fully described subsequently. Further, the timing apparatus 510 20 comprises a group of relays, including a signal relay R520, a start relay R530 and three timer relays R540, R545 and R550, connected and arranged in a manner more fully described subsequently.

Preferably, each set of tone apparatus is identical to the tone apparatus 600, shown in Fig. 6, 30 which comprises an amplifier including the thermionic discharge tube 680 having its input electrodes 683 and 684 arranged to be coupled to the tone condenser 674 through a coupling transformer 660, and provided with an output circuit 35 comprising a resistance capacitance coupling network through which amplified signal voltages are impressed between the input electrodes 677 and 678 of the control tube 675. More specifically, the network coupling the input electrodes of the control tube 675 with the output electrodes of the amplifier tube 680 comprises a coupling condenser 635 and a resistor 636. For the purpose of supplying energizing current to the filamentary cathode 678 of the control tube 675 and the 40 cathode heater 685 of the amplifier tube 680, and for the additional purpose of providing anode and screen potentials for the tubes 675 and 680, a power pack is provided which comprises a power transformer 650, a full-wave rectifier tube 670 and a filter network including the series connected choke 640 and the shunt connected filter condensers 633 and 634. More specifically, the 45 output circuit of the power pack includes the series connected circuit elements 640, 641, 644 and 645, anode potential being impressed upon the anode 676 of the control tube 675 through the winding of the slow-to-release relay R615, and appropriate potentials being applied to the screen and anode electrodes 682 and 681 of the amplifier tube 680 through the impedance elements 643 and 642, respectively. The tone apparatus 600 also includes a group of relays including the above-mentioned tone relay R615, a start relay R610, a pair of control relays R620 and R625 50 and a switch relay R630. These relays are connected and arranged to operate in a manner more fully described hereinafter.

A better understanding of the connection and arrangement of the apparatus incorporated in the telephone system will be facilitated from a consideration of the detailed operation of the various pieces of apparatus incident to the handling of the various toll and trunk calls at the switchboard, as will appear hereinafter.

*Extension of calls to the switchboard in the
P. A. B. X.*

In order to extend a call from a subscriber substation, such as the subscriber substation T4, in the P. A. B. X. 30 to the switchboard therein, a call operation is first performed at the calling subscriber substation T4, thereby to cause the line circuit 231 individually associated with the telephone line 230 extending to the subscriber substation T4 to operate. Upon operating, the line circuit 231 initiates operation of one of the local finder-selector links, such as the local finder-selector link 235, in the local switch train, whereupon the local finder-selector link 235 operates to seize the telephone line 230. When the telephone line 230 extending to the calling subscriber substation T4 is thus seized the line circuit 231 operates in order to mark the telephone line 230 as busy to the local connectors having access thereto; and the local finder-selector link 235 is rendered operative to a digit dialed thereto. The subscriber at the subscriber substation T4 then dials a predetermined digit therat, thereby to cause the local finder-selector link 235 to operate and select an idle trunk in the associated group of trunks, such, for example, as the trunk 243 extending to the trunk circuit 241. When the trunk circuit 241 is thus seized it operates to mark the trunk 243 extending thereto as a calling trunk in the contact banks of the switching links having access thereto, and to initiate operation, by way of the start conductor C242 of the distributor 250; whereupon the distributor 250 operates to initiate operation of the finder of a previously prepared one of the switching links at a preselected one of the operator positions at the switchboard. Assuming that the switching link illustrated, individually associated with the first operator position 301 at the switchboard, has been previously prepared and that the first operator position 301 has been preselected by the distributor 250, the distributor 250 operates to initiate operation of the finder 300 of the switching link illustrated. The finder 300 of the switching link illustrated operates in order to seize the trunk 243 extending to the trunk circuit 241, thereby to complete an obvious connection between the calling subscriber substation T4 and the first operator position 301. The operator at the first operator position 301 then answers the call and is informed by the subscriber at the calling subscriber substation T4 concerning the extension of the call, in the event this is necessary.

Subsequently, after the termination of the connection the switching link illustrated is released automatically or manually by the operator at the first operator position 301, in a manner more fully explained hereinafter; whereupon the local finder-selector link 235 is released, assuming that the subscriber at the calling subscriber substation T4 has replaced the receiver of the telephone instrument therat upon its associated switchhook at this time; and the line circuit 231 operates in order to mark the telephone line 230 extending to the subscriber substation T4 as idle to the local connectors having access thereto.

In order to extend a call from the central office 20 to the switchboard in the P. A. B. X. 30, the operator at the operator position 201 in the central office 20 first selects an idle trunk line in the group of trunk lines extending from the central office 20 to the P. A. B. X. 30, such as the trunk line 203, and then operates the apparatus at the operator position 201, thereby to cause

ringing current to be projected over the trunk line 203. The projection of ringing current over the trunk line 203 initiates operation of the trunk circuit 205. Upon operating, the trunk circuit 205 marks the trunk 207 extending thereto as a calling trunk in the contact banks of the switching links having access thereto and initiates operation, by way of the start conductor C206 of the distributor 250; whereupon the distributor 250 operates to initiate operation of the finder of a previously prepared one of the switching links at a preselected one of the operator positions at the switchboard. Assuming that the switching link illustrated, individually associated with the first operator position 301 at the switchboard, has been previously prepared and that the first operator position 301 has been preselected by the distributor 250, the distributor 250 operates to initiate operation of the finder 300 of the switching link illustrated. The finder 300 of the switching link illustrated operates in order to seize the trunk 207 extending to the trunk circuit 205, thereby to complete an obvious connection between the operator position 201 in the central office 20 and the first operator position 301. The operator at the first operator position 301 then answers the call and is informed by the operator at the operator position 201 concerning the extension of the call, in the event this is necessary.

Subsequently, after the termination of the connection the switching link illustrated is released automatically or manually by the operator at the first operator position 301, in a manner more fully explained hereinafter, whereupon the trunk line 203 extending from the central office 20 to the P. A. B. X. 30 is rendered idle, assuming that the operator at the operator position 201 in the central office 20 has disconnected from the trunk line 203 at this time.

In order to extend a call from the I. B. X. 40 to the switchboard in the P. A. B. X. 30, the operator at the operator position 217 in the I. B. X. 40 first selects an idle trunk line in the group of trunk lines extending between the I. B. X. 40 and the P. A. B. X. 30, such as the trunk line 220, and then establishes a connection thereto. When a connection is established at the operator position 217 in the I. B. X. 40 to the trunk line 220 the trunk circuit 221 associated therewith operates. Upon operating, the trunk circuit 221 marks the trunk 222 extending thereto as a calling trunk in the contact banks of the switching links having access thereto, marks the trunk 506 extending thereto as busy to the toll connectors having access thereto, and initiates operation, by way of the start conductor C223 of the distributor 250; whereupon the distributor 250 operates to initiate operation of the finder of a previously prepared one of the switching links at a preselected one of the operator positions at the switchboard. Assuming that the switching link illustrated, individually associated with the first operator position 301 at the switchboard, has been previously prepared and that the first operator position 301 has been preselected by the distributor 250, the distributor 250 operates to initiate operation of the finder 300 of the switching link illustrated. The finder 300 of the switching link illustrated operates in order to seize the trunk 222 extending to the trunk circuit 221, thereby to complete an obvious connection between the operator position 217 in the I. B. X. 40 and the first operator position 301. The operator at the first operator position 301 then an-

swers the call and is informed by the operator at the operator position 217 concerning the extension of the call in the event this is necessary.

Subsequently, after the termination of the connection the switching link illustrated is released automatically or manually by the operator at the first operator position 301, in a manner more fully explained hereinafter; whereupon the trunk line 220 extending between the I. B. X. 40 and the P. A. B. X. 30 is rendered idle, assuming that the operator at the operator position 217 in the I. B. X. 40 has disconnected from the trunk line 220 at this time. The trunk circuit 221 then operates in order to mark the trunk 506 extending thereto as idle to the toll connectors having access thereto.

In order to extend a call from the distant exchange 50 to the switchboard in the P. A. B. X. 30, the operator at the toll operator position 225 in the distant exchange 50 first selects an idle toll line in the group of toll lines extending between the distant exchange 50 and the P. A. B. X. 30, such as the toll line 226, and then operates the apparatus at the toll operator position 225, thereby to cause ringing current to be projected over the toll line 226. The projection of ringing current over the toll line 226 initiates operation of the toll line circuit 227. Upon operating, the toll line circuit 227 marks the trunk 228 extending thereto as a calling trunk in the contact banks of the switching links having access thereto; marks the trunk 507 extending thereto as busy to the toll connectors having access thereto; and initiates operation, by way of the start conductor C229 of the distributor 250; whereupon the distributor 250 operates to initiate operation of the finder of a previously prepared one of the switching links at a preselected one of the operator positions at the switchboard. Assuming that the switching link illustrated, individually associated with the first operator position 301 at the switchboard, has been previously prepared and that the first operator position 301 has been preselected by the distributor 250, the distributor 250 operates to initiate operation of the finder 300 of the switching link illustrated. The finder 300 of the switching link illustrated operates in order to seize the trunk 228 extending to the toll line circuit 227, thereby to complete an obvious connection between the toll operator position 225 in the distant exchange 50 and the first operator position 301. The operator at the first operator position 301 then answers the call and is informed by the operator at the toll operator position 225 concerning the extension of the call, in the event this is necessary.

Subsequently, after the termination of the connection the switching link illustrated is released automatically or manually by the operator at the first operator position 301, in a manner more fully explained hereinafter; whereupon the toll line 226 extending between the distant exchange 50 and the P. A. B. X. 30 is rendered idle, assuming that the operator at the toll operator position 225 in the distant exchange 50 has disconnected from the toll line 226 at this time. The toll line circuit 227 then operates in order to mark the trunk 507 extending thereto as idle to the toll connectors having access thereto.

Extension of calls from the switchboard in the P. A. B. X.

In order to extend a call from one of the operator positions, such as the first operator position 301, at the switchboard in the P. A. B. X. 30

which has been previously answered on one of the switching links associated therewith, such as the switching link illustrated, the operator at the first operator position 301 first operates the position digit keys thereat, thereby to cause one or more digits corresponding to the route over which the call is to be extended to be registered in the associated digit register sender apparatus. The digit register sender apparatus then operates in order to cause the digits registered to be transmitted to the first selector 500 of the switching link illustrated.

Assuming that the call is to be extended to a subscriber substation, such as the subscriber substation T3, in the P. A. B. X. 30, the first selector 500 operates to seize a trunk extending to an idle second selector, such as the trunk 503 extending to the second selector 505. The second selector 505 then operates in order to seize a trunk extending to an idle local connector, such as the trunk 508, extending to the local connector 236. The local connector 236 then operates in order to select the telephone line 232 extending to the called subscriber substation T3. The local connector 236 then operates to test the idle or busy condition of the selected subscriber line 232, in accordance with conventional practice. The subsequent operation of the local connector 236 depends upon the idle or busy condition of the subscriber line 232 extending to the called subscriber substation T3. In the event the called subscriber substation T3 is idle at this time, ringing current is projected from the local connector over the subscriber line 232 to the called subscriber substation T3 in order to operate the ringer thereat; while ring-back tone current is returned over the trunk 508 the second selector 505, the trunk 503 and the first selector 500 to the finder 300, and thereover to the calling connection. On the other hand, in the event the called subscriber substation T3 is busy at this time, busy tone current is returned over the previously traced connection to the finder 300 and thereover to the calling connection. Assuming that the called subscriber substation T3 is idle at this time, the line circuit 233 associated with the telephone line 232 extending thereto operates incident to seizure of the telephone line 232 by the local connector 236 in order to mark the telephone line 232 as busy to the other local connectors having access thereto.

At this point, it is noted that the operator at the first operator position 301 disconnects the link illustrated from the first operator position after operating the position digit keys when the connection is extended to a subscriber substation in the P. A. B. X. 30. Further, it is noted that, in the event the called subscriber substation T3 is busy, the busy tone current returned from the local connector 236 over the previously traced connection to the finder 300 is not only returned therefrom to the calling connection, but this busy tone current returned to the finder 300 initiates operation of the tone apparatus 600 in order to cause flashing of the hold lamp L409 associated with the link illustrated at the first operator position 301, in a manner more fully explained hereinafter.

Subsequent to the termination of the connection the switching link illustrated is automatically released. When the switching link illustrated is thus released the second selector 505 and the local connector 236 are released; whereupon the line circuit 233 is operated in order to mark the telephone line 232 as idle to the local

connectors having access thereto, assuming that the subscriber at the subscriber substation T3 has replaced the receiver of the telephone instrument thereat upon its associated switchhook at this time.

Assuming that the call is to be extended to the central ofice 20, the first selector 500 operates to seize a trunk extending to an idle toll connector, such as the trunk 502 extending to the toll connector 504. The toll connector 504 then operates to seize a trunk extending to an idle repeater, such as the trunk 501 extending to the repeater 204.

At this point, it is noted that the operator at the first operator position 301 retains the connection between the first operator position 301 and the link illustrated when a connection is extended to the central office 20. Accordingly, after the toll connector 504 seizes the trunk 501 extending to the repeater 204, the operator at the first operator position operates the position apparatus thereat, thereby to cause ringing current to be projected over the trunk 501, the repeater 204 and the trunk line 202 to the operator position 201 in the central office 20. The projection of ringing current over the trunk line 202 extending from the P. A. B. X. 30 to the central office 20 causes apparatus at the operator position 201 in the central office 20 to be operated in order to indicate to the operator thereat that a call is extended to the operator position 201. The operator at the operator position 201 then answers the call and is advised by the operator at the first operator position 301 concerning the further extension of the call. The operator at the first operator position 301 then disconnects the link illustrated from the first operator position.

Subsequent to the termination of the connection, the operator at the first operator position 301 again connects the switching link illustrated to the first operator position 301 and then operates the position apparatus thereat, thereby to cause the release of this switching link. When the switching link illustrated is thus released the trunk line 202 is rendered idle, assuming that the operator at the operator position 201 in the central office 20 has disconnected therefrom at this time.

Assuming that the call is to be extended to the I. B. X. 40, the first selector 500 operates to seize a trunk extending to an idle toll connector, such as the trunk 502 extending to the toll connector 504. The toll connector 504 then operates to seize a trunk extending to an idle trunk circuit, such as the trunk 506, extending to the trunk circuit 221.

At this point, it is noted that the operator at the first operator position 301 retains the connection between the first operator position 301 and the link illustrated when a connection is extended to the I. B. X. 40. Accordingly, after the toll connector 504 seizes the trunk 506 extending to the trunk circuit 221, the operator at the first operator position 301 operates the position apparatus thereat, thereby to cause ringing current to be projected over the trunk 506, the trunk circuit 221 and the trunk line 220 to the operator position 217 in the I. B. X. 40. The projection of ringing current over the trunk line 220 extending between the P. A. B. X. 30 and the I. B. X. 40 causes apparatus at the operator position 217 in the I. B. X. 40 to be operated in order to indicate to the operator thereat that a call is extended to the operator position 217.

The operator at the operator position 217 then answers the call and is advised by the operator at the first operator position 301 concerning the further extension of the call. The operator at the first operator position 301 then disconnects the link illustrated from the first operator position 301.

Subsequent to the termination of the connection, the operator at the first operator position 301 again connects the switching link illustrated to the first operator position 301 and then operates the position apparatus thereat, thereby to cause the release of this switching link. When the switching link illustrated is thus released the toll connector 504 is released; whereupon the trunk line 220 is rendered idle, assuming that the operator at the operator position 217 in the I. B. X. 40 has disconnected therefrom at this time.

Assuming that the call is to be extended to the distant exchange 50, the first selector 500 operates to seize a trunk extending to an idle toll connector, such as the trunk 502 extending to the toll connector 504. The toll connector 504 then operates to seize a trunk extending to an idle toll line circuit, such as the trunk 507 extending to the toll line circuit 227.

At this point, it is noted that the operator at the first operator position 301 retains the connection between the first operator position 301 and the link illustrated when a connection is extended to the distant exchange 50. Accordingly, after the toll connector 504 seizes the trunk 507 extending to the toll line circuit 227, the operator at the first operator position 301 operates the position apparatus thereat, thereby to cause ringing current to be projected over the trunk 507, the toll line circuit 227 and the toll line 226 to the toll operator position 225 in the distant exchange 50. The projection of ringing current over the toll line 226 extending between the P. A. B. X. 30 and the distant exchange 50 causes apparatus at the toll operator position 225 in the distant exchange 50 to be operated in order to indicate to the operator thereat that a call is extended to the toll operator position 225. The operator at the toll operator position 225 then answers the call and is advised by the operator at the first operator position 301 concerning the further extension of the call. The operator at the first operator position 301 then disconnects the link illustrated from the first operator position.

Subsequent to the termination of the connection, the operator at the first operator position 301 again connects the switching link illustrated to the first operator position 301 and then operates the position apparatus thereat, thereby to cause the release of this switching link. When the switching link illustrated is thus released the toll connector 504 is released; whereupon the toll line 226 is rendered idle, assuming that the operator at the toll operator position 225 in the distant exchange 50 has disconnected therefrom at this time.

Detailed operation of the finder of a switching link to extend a call to the associated operator position at the switchboard in the P. A. B. X.

When the operator at any one of the operator positions, such as the first operator position 301, at the switchboard in the P. A. B. X. 30 is not engaged, she selects an idle one of the associated switching links, such as the switching link illustrated, and prepares it for use. The operator at

the first operator position 301 prepares the switching link illustrated for use by operating the talk key K380 thereof, this switching link being designated as idle by the extinguished condition of the busy lamp L326. When the talk key K380 is thus operated a circuit is completed, at the contacts 383 thereof, for energizing the upper winding of the talk relay R370, this circuit including the grounded preparatory conductor C306 in the cable 302 extending to the first operator position 301. When thus energized the talk relay R370 operates to complete, at the contacts 373', an obvious holding circuit, including the contacts 384 of the talk key K380 and the grounded hold conductor C305 in the cable 302 extending to the first operator position 301, for energizing the lower winding thereof. When this holding circuit is completed one of the position relays in the position equipment at the first operator position 301 operates in order to remove ground potential from the preparatory conductor C306, whereupon the previously mentioned circuit for energizing the upper winding of the talk relay R370 is interrupted. Thus, it will be understood that the operation of the talk relay R370 in the switching link illustrated is effective to prevent the operation of the talk relay in any of the other switching links associated with the first operator position 301. Hence, the operation of the talk key K380 of the switching link illustrated is effective to connect this switching link to the cable 302 extending to the first operator position 301 and to prevent any of the other switching links associated with the cable 302 from being connected thereto at this time.

Also, when the previously mentioned holding circuit for energizing the lower winding of the talk relay R370 is completed, the position equipment at the first operator position 301 is rendered effective to answer a call routed thereto by way of the switching link illustrated and the distributor 250 is controlled, thereby to mark the first operator position 301 as selectable thereto; whereupon the distributor 250 selects the first operator position 301 in due course, the distributor 250 being operative automatically to select the ones of the operator positions at the switchboard marked as selectable thereto, in a predetermined order.

Also, the talk relay R370 prepares, at the contacts 372', a circuit traced hereinafter for energizing the lower winding of the start relay R360, this circuit including the start conductor C381 extending by way of the cable 302, the position equipment at the first operator position 301 and the cable 238 to the distributor 250. Further, the talk relay R370 interrupts, at the contacts 373 and 376, a partially prepared connection, traced hereinafter, between the finder 300 and the first selector 500, prepares, at the contacts 372 and 375, a connection, traced hereinafter, between the finder 300 and the first operator position 301, and prepares, at the contacts 371 and 374, a connection, traced hereinafter, between the first selector 500 and the first operator position 301. Further, the talk relay R370 interrupts, at the contacts 377, a multiple circuit, traced hereinafter, for illuminating the busy lamp L326, prepares, at the contacts 378, a circuit traced hereinafter for illuminating the identity lamps associated with the various trunk and toll circuits, prepares, at the contacts 379, a path, traced hereinafter, for marking the switching link illustrated to be seized by the register sender apparatus at the first operator posi-

tion 301, prepares, at the contacts 370, a path including the release answer conductor C383, traced hereinafter, for short-circuiting the upper winding of the start relay R360, and prepares, at the contacts 371', a circuit including the release call conductor C382, traced hereinafter, for short-circuiting the winding of the cut-in relay R430.

When a call arrives at the switchboard, operation of the distributor 250 is initiated, as previously explained, whereupon ground potential therein is applied by way of the cable 238 and the position equipment at the first operator position 301 to the start conductor C381 in the cable 302, assuming that the distributor 250 has selected the first operator position 301 at this time. The application of ground potential to the start conductor C381 completes the previously mentioned circuit for energizing the lower winding of the start relay R360, this circuit extending from the grounded start conductor C381 by way of the contacts 372', the set of switch springs C325 and the lower winding of R360 to battery. When thus energized the start relay R360 operates to complete, at the contacts 361, an obvious circuit for illuminating the busy lamp L326, the illumination of the busy lamp L326 designating the switching link illustrated as busy. Also, the start relay R360 prepares, at the contacts 362, a holding circuit, traced hereinafter, for energizing the upper winding thereof, and completes, at the contacts 363, an obvious path for applying ground potential to the hold conductor C389. Finally, the start relay R360 completes, at the contacts 365, an obvious holding circuit, including the set of switch springs S323 and the grounded start conductor C381, for energizing the lower winding thereof.

The application of ground potential to the hold conductor C389 completes an obvious circuit for illuminating the hold lamp L409 and an obvious multiple circuit for energizing the lower winding of the cut-through relay R330. When the lower winding of the cut-through relay R330 is thus energized this relay is rendered exceedingly fast to operate when the upper winding thereof is subsequently energized. Also, the application of ground potential to the hold conductor C389 completes an obvious circuit, including the contacts 337, 352 and 345, for energizing the vertical magnet M320. When thus energized the vertical magnet M320 operates, thereby to drive the wiper carriage of the Strowger mechanism 310 one step in the vertical direction and to complete, at the contacts 321, an obvious circuit for energizing the winding of the step relay R350. When thus energized the step relay R350 operates to interrupt, at the contacts 352, the previously traced circuit for energizing the vertical magnet M320, thereby to cause the vertical magnet M320 to restore. Upon restoring, the vertical magnet M320 interrupts, at the contacts 321, the previously mentioned circuit for energizing the winding of the step relay R350, thereby to cause the latter relay to restore and recomplete, at the contacts 352, the previously traced circuit for energizing the vertical magnet M320. The vertical magnet M320 and the step relay R350 interact in the manner described above, thereby to drive the wiper carriage of the Strowger mechanism 310 step by step in the vertical direction until the level in the associated main contact bank terminating the calling trunk is reached, whereupon a circuit is completed for energizing the lower winding of the transfer re-

lay R340. The circuit for energizing the lower winding of the transfer relay R340 extends from the grounded contact in the vertical control contact bank engaged by the vertical control wiper 317 by way of the contacts 343, the lower winding of R340, the contacts 351 and 345 and the vertical magnet M320 to battery. When this series circuit is completed the vertical magnet M320 remains in its operated position, thereby to retain the step relay R350 in its operated position; and shortly thereafter the transfer relay R340 operates, this relay being of the slow-to-operate type. Upon operating, the transfer relay R340 completes, at the contacts 342, an obvious circuit, including the contacts 337 and the grounded hold conductor C389, for energizing the upper winding thereof. Also, the transfer relay R340 interrupts, at the contacts 341, a point in the previously mentioned circuit for illuminating the identity lamp associated with the calling trunk or toll line circuit, and interrupts, at the contacts 343 and 345, the previously traced circuit for energizing the lower winding thereof in series with the vertical magnet M320. The vertical magnet M320 then restores, thereby to interrupt, at the contacts 321, the previously mentioned circuit for energizing the winding of the step relay R350, thereby to cause the latter relay to restore.

It is noted that, when the wiper carriage of the Strowger mechanism 310 is driven one step in the vertical direction, the set of switch springs S324 is actuated into engagement, thereby to prepare an obvious circuit for energizing the release magnet M322; and the set of switch springs S325 is actuated into disengagement, thereby to interrupt a point in the previously traced original circuit for energizing the lower winding of the start relay R360. However, the previously traced holding circuit for energizing the lower winding of the start relay R360 is completed at this time, as the set of switch springs S323 is actuated only in the event the wiper carriage of the Strowger mechanism 310 is driven eleven steps in the rotary direction away from its normal position.

Upon restoring, the step relay R350 completes, at the contacts 352, a circuit for energizing the rotary magnet M318, this circuit extending from the grounded hold conductor C389 by way of the contacts 337, 352 and 344 and the rotary magnet M318 to battery. When thus energized the rotary magnet M318 operates to drive the wiper carriage of the Strowger mechanism 310 one step in the rotary direction and to complete, at the contacts 319, an obvious circuit for energizing the winding of the step relay R350, thereby to cause the latter relay to operate. Upon operating, the step relay R350 interrupts, at the contacts 352, the previously traced circuit for energizing the rotary magnet M318, thereby to cause the rotary magnet M318 to restore and interrupt, at the contacts 319, the previously mentioned circuit for energizing the winding of the step relay R350. The step relay R350 then restores to recomplete, at the contacts 352, the previously traced circuit for energizing the rotary magnet M318. The rotary magnet M318 and the step relay R350 interact, in the manner described above, in order to cause the wiper carriage of the Strowger mechanism 310 to be driven step by step in the rotary direction until the position of the calling trunk in the associated main contact bank is reached, whereupon a circuit is

completed for energizing the upper winding of the cut-through relay R330.

The circuit for energizing the upper winding of the cut-through relay R330 extends from the 5 grounded hold conductor C389 by way of the upper winding of R330, the control wiper 316 and the engaged contact in the associated main contact bank having battery potential thereon. When thus energized the cut-through relay R330 10 operates to complete, at the contacts 335, an obvious holding circuit, including the grounded hold conductor C389, for energizing the intermediate winding thereof. Also, the cut-through relay R330 completes, at the contacts 336, an obvious path, including the grounded hold conductor C389, for applying direct ground potential to the control wiper 316, thereby to cause the trunk or toll line circuit associated with the trunk seized by the wiper carriage of the Strowger mechanism 310 to switch through. Also, the cut-through relay R330 interrupts, at the contacts 337, the previously traced circuit for energizing the rotary magnet M318, thereby to cause the rotary magnet M318 to restore, whereupon further operation thereof is arrested. Upon restoring, the rotary magnet M318 interrupts, at the contacts 319, the previously mentioned circuit for energizing the winding of the step relay R350, thereby to cause the latter relay to restore. Further, the cut-through relay R330 15 interrupts, at the contacts 337, the previously traced holding circuit for energizing the upper winding of the transfer relay R340, thereby to cause the latter relay to restore. Upon restoring, the transfer relay R340 completes, at the contacts 341, an obvious path, including the contacts 378, for applying ground potential to the identity wiper 314, thereby to cause the identity lamp associated with the trunk or toll line circuit seized by the wiper carriage of the Strowger mechanism 310 to be illuminated. The illumination of the identity lamp associated with the trunk or toll line circuit seized by the wiper carriage of the Strowger mechanism 310 indicates to the operator at the first operator position 301 the group and, consequently, the general character of the calling trunk seized.

Further, the cut-through relay R330 completes, at the contacts 334, the previously mentioned holding circuit for energizing the upper winding of the start relay R360, this circuit extending from ground by way of the contacts 334 and 362, the upper winding of R360, C565 and the resistor 328 to battery. Further, the cut-through relay R330 completes, at the contacts 331 and 332, a connection between the seized trunk and the first operator position 301, this connection extending from the two line conductors of the seized trunk by way of the line wipers 311 and 312 of the wiper carriage of the Strowger mechanism 310, the contacts 331, 332 and 372, 375 to the answer conductors C387 and C385, respectively, in the cable 302 extending to the first operator position 301. Accordingly, at this time, an operative connection is completed between the calling trunk and the first operator position 301, whereupon the position apparatus at the first operator position 301 operates to transmit a seizure tone to the receiver thereof in order to indicate to the operator at the first operator position 301 that a call has arrived. The operator at the first operator position 301 then communicates with the calling subscriber or operator and is advised concerning the extension of the call.

Finally, it is noted that, upon operating, the cut-through relay R330 prepares, at the contacts 333, an obvious path, including the discrimination wiper 313, for applying ground potential to the discrimination conductor C573 extending into the first selector 500 in the event the seized trunk is of a particular type requiring class recording. In this event, the trunk circuit seized by the wiper carriage of the Strowger mechanism 310 comprises a grounded discrimination lead connected to the contact in the main contact bank engaged by the discrimination wiper 313 of the wiper carriage of the Strowger mechanism 310, whereupon ground potential is applied to the discrimination conductor C573, as previously explained. The application of ground potential to the discrimination conductor C573 is effective to cause class recording apparatus in the first selector 500 to operate.

Also, it is noted that, when the previously mentioned connection between the calling trunk and the first operator position 301 is completed, the position equipment at the first operator position 301 operates in order to cause operation of the register sender apparatus to be initiated, whereupon the register sender apparatus is automatically associated with the switching link illustrated, the switching link illustrated being marked for association with the register sender apparatus due to the presence of battery potential upon the marking conductor C384 in the cable 302 extending to the first operator position 301. The path for applying battery potential to the marking conductor C384 extends from battery potential in the first selector 500 by way of C574 and the contacts 434 and 379 to the marking conductor C384. Accordingly, at this time, the register sender apparatus is associated with the switching link illustrated, and the first selector 500 is in readiness to receive digits transmitted thereto from the register sender apparatus.

Detailed operation of the first selector of a switching link to extend a call from the associated operator position at the switchboard in the P. A. B. X.

By way of example, the operation of the first selector 500 of the switching link illustrated at the first operator position 301 at the switchboard to extend a call from the first operator position 301 will be continued. The operator at the first operator position 301 now operates the digit keys included in the position equipment thereat, whereupon digits are registered in the register sender apparatus. The digits registered in the digit register sender apparatus at the first operator position 301 are transmitted by way of the line conductors C571 and C572 into the first selector 500, thereby to cause operation thereof in accordance with conventional practice.

In the event the call is extended to the central office 20, the I. B. X. 40 or the P. A. B. X. 30, it is routed by way of one of the toll connectors, such as the toll connector 504, as previously noted, and the operator at the first operator position 301 retains the connection to the switching link illustrated by retaining the talk key K380 in its operated position. In this event, when the first selector 500 seizes the trunk 502 extending to the toll connector 504, an obvious circuit is completed for energizing the winding of the toll relay R400, thereby to cause the latter relay to operate. Upon operating, the toll relay R400 completes, at the

contacts 402, an obvious multiple circuit for illuminating the busy lamp L326 and an obvious multiple circuit for energizing the upper winding of the supervisory relay R425. However, this relay does not operate at this time, as it is of the differential type. Further, the toll relay R400 interrupts, at the contacts 403, a point in a path traced hereinafter for applying ground potential to the start conductor C563 10 extending into the timer apparatus 510, thereby to prevent operation of the timer apparatus 510 at this time. Also, the toll relay R400 interrupts, at the contacts 401, a point in a circuit traced hereinafter for energizing the windings 15 of the supervisory relays R410 and R420, thereby to prevent operation thereof at this time. Further, the toll relay R400 completes, at the contacts 404, a multiple circuit, including the resistor 407, with the previously traced holding 20 circuit for energizing the upper winding of the start relay R360. When this multiple circuit is completed, the upper winding of the start relay R360 is partially deenergized. However, the latter relay remains in its operated position at 25 this time and is rendered fast to release under the control of the operator at the first operator position 301, in a manner more fully explained subsequently. Finally, the toll relay R400 prepares, at the contacts 405, a point in a circuit 30 traced hereinafter for illuminating the supervisory lamp L327.

When all of the digits registered in the digit register sender apparatus in the position equipment at the first operator position 301 have been 35 transmitted to the first selector 500, the digit register sender apparatus operates to cause ground potential to be applied to the cut-in conductor C308 in the cable 302. This application of ground potential to the cut-in conductor C308 40 completes an obvious circuit, including the contacts 438 and the resistor 408, for energizing the winding of the cut-in relay R430, thereby to cause the latter relay to operate. Upon operating, the cut-in relay R430 completes, at the contacts 437, an obvious holding circuit, including the grounded hold conductor C389 and the resistor 408, for energizing the winding thereof. Further, the cut-in relay R430 interrupts, at the contacts 438, the previously traced original circuit 45 for energizing the winding thereof, including the cut-in conductor C308 in the cable 302. Further, the cut-in relay R430 interrupts, at the contacts 436, the previously traced circuit for illuminating the hold lamp L409. The extinguishment of the hold lamp L409 indicates to the operator at the first operator position 301 50 that all of the digits registered in the digit register sender apparatus have been transmitted and that the connection has been extended by way of the first selector 500.

Also, the cut-in relay R430 interrupts, at the contacts 434, the previously traced path for applying battery potential in the first selector 500 to the marking conductor C384 in the cable 302, thereby to cause the digit register sender apparatus in the position equipment at the first operator position 301 to be released. Further, the cut-in relay R430 completes, at the contacts 435, an obvious path for applying ground potential to the hold conductor C574 extending into the first selector 500, thereby to retain the first selector 500 and the toll connector 504 in their operated positions. Further, the cut-in relay R430 completes, at the contacts 431 and 432, a connection between the first selector 500 and

the first operator position 301, this connection extending from the first selector 500 by way of the line conductors C571 and C572, the contacts 431 and 432, the condenser 450 and the lower winding of the supervisory relay R425 in multiple, the line conductors C444 and C445 and the contacts 371 and 374 to the call conductors C388 and C386 in the cable 302 extending to the first operator position 301. Also, it is noted that the lower winding of the supervisory relay R425 is bridged by the condenser 450, thereby to provide a connection between the first operator position 301 and the first selector 500, excluding the lower winding of the supervisory relay R425, for the transmission of signal currents. Further, the connection extends from the first selector 500 by way of the trunk 502, the toll connector 504 and one of the trunks to one of the trunk circuits or to one of the toll line circuits. At this point, it is noted that the connection between the first operator position 301 and the trunk circuit or toll line circuit comprises a dry loop, whereby the lower winding of the supervisory relay R425 is not energized.

Upon observing the extinguishment of the hold lamp L409, the operator at the first operator position 301 momentarily operates the position ring key in the position equipment at the first operator position 301, thereby to cause ringing current to be projected over the called connection to the operator position involved therein. After the operator at the operator position involved in the called connection answers the call the operator at the first operator position 301 advises her concerning the further extension of the call and then disconnects the switching link illustrated from the first operator position 301 by returning the talk key K380 to its normal position, whereupon a direct connection is completed by way of the switching link illustrated between the calling connection and the called connection.

When the talk key K380 is returned to its normal position there is interrupted, at the contacts 384 thereof, the previously traced holding circuit for energizing the lower winding of the talk relay R370, including the hold conductor C305, thereby to cause the talk relay R370 to restore. Upon restoring, the talk relay R370 interrupts, at the contacts 373, a point in the previously traced holding circuit for energizing the lower winding thereof, whereupon the position relays in the position equipment at the first operator position 301 operate in order to cause ground potential to be reconnected to the preparatory conductor C306; whereupon the talk keys of the other switching links associated with the first operator position 301 are rendered operative to connect the other switching links to the first operator position 301. Further, the talk relay R370 interrupts, at the contacts 372, a further point in the previously traced circuit for energizing the lower winding of the start relay R360, interrupts, at the contacts 371, a further point in the previously mentioned path for short-circuiting the winding of the cut-in relay R430, including the release call conductor C382, and interrupts, at the contacts 370, a further point in the previously mentioned path for short-circuiting the upper winding of the start relay R360, including the release answer conductor C383. Further, the talk relay R370 interrupts, at the contacts 379, a further point in the previously mentioned connection between the marking conductor C384 in the cable 302 and 75

the hold conductor C574 extending into the first selector 500; and interrupts, at the contacts 378, the previously traced circuit for illuminating the identity lamp associated with the calling trunk or toll line circuit seized by the wiper carriage of the Strowger mechanism 310. Also, the talk relay R370 completes, at the contacts 377, an obvious multiple circuit, including the contacts 432, for illuminating the busy lamp L326, interrupts, at the contacts 372 and 375, the connection between the finder 300 and the answer conductors C387 and C385, interrupts, at the contacts 371 and 374, the connection between the first selector 500 and the call conductors C388 and C386, and completes, at the contacts 373 and 376, an obvious connection between the finder 300 and the first selector 500. At this time, a direct connection is completed by way of the switching link illustrated between the calling connection and the called connection.

On the other hand, in the event the call is extended to a local subscriber substation in the P. A. B. X. 30, it is routed by way of one of the second selectors, such as the second selector 505, as previously noted; and the operator at the first operator position 301 disconnects from the switching link illustrated by restoring the talk key K380 after all of the digits have been registered in the digit register sender apparatus. In this event, when the first selector 500 seizes the trunk 503 extending to the second selector 505, the previously mentioned circuit for energizing the winding of the toll relay R400 is not completed, thereby to prevent operation of the latter relay at this time.

When the talk key K380 is returned to its normal position the talk relay R370 restores, thereby to complete the previously traced connection between the finder 300 and the first selector 500 incident to the operation of the cut-in relay R430, in the manner previously explained. When all of the digits registered in the digit register sender apparatus in the position equipment at the first operator position 301 have been transmitted, the cut-in relay R430 operates, in the manner previously explained, thereby to complete the previously mentioned connection between the finder 300 and the first selector 500. At this time, the connection is further extended from the first selector 500 by way of the trunk 503 and the second selector 505 to one of the local connectors in the local switch train, such as the local connector 236. Thus, the second selector 505 has seized the trunk 508 extending to the local connector 236 and the local connector 236 has operated to select the called telephone line.

At this point, it is noted that the connection extending between the trunk circuit or the toll line circuit seized by the wiper carriage of the Strowger mechanism 310 and the local connector 236, and including the finder 300, the first selector 500, the trunk 503, the second selector 505 and the trunk 508, is of the battery feed type, whereby the previously traced circuit for energizing the lower winding of the supervisory relay R425 is completed. However, the supervisory relay R425 is not operated at this time as it is of the differential type, as previously noted.

At this time, the local connector 236 operates to test the idle or busy condition of the selected telephone line, whereupon either ring-back tone current or busy tone current is returned over

the previously traced connection to the finder 300, in the manner previously explained.

Neglecting for the present the operation of the finder 300, in response to the ring-back tone current or busy tone current returned thereto, and assuming that the telephone line selected by the local connector 236 is idle and that the call is answered promptly, when the call is answered at the called subscriber substation associated with the telephone line seized by the local connector, the local connector 236 operates to reverse battery back over the previously traced connection, including the finder 300. When the battery is reversed back over the finder 300 the lower winding of the supervisory relay R425 is energized in the same direction as the upper winding thereof, thereby to cause the latter relay to operate. Prior to operation of the supervisory relay R425 and incident to the operation of the cut-in relay R430, the previously mentioned path for applying ground potential to the start conductor C563 extending into the timer apparatus 510 is completed, this path extending from ground by way of the contacts 361, 371, 401, 433, 421, 422 and 403 to the start conductor C563. The application of ground potential to the start conductor C563 extending into the timer apparatus 510 initiates operation thereof, in a manner more fully explained hereinafter. Upon operating, the supervisory relay R425 interrupts, at the contacts 427, the previously traced path for applying ground potential to the start conductor C563 extending into the timer apparatus 510, thereby to arrest further operation thereof at this time. Further, the supervisory relay R425 completes, at the contacts 426, a circuit substantially identical to that previously traced for energizing the winding of the supervisory relay R420, thereby to cause the latter relay to operate, for a purpose more fully explained hereinafter. At this time, an operative connection is completed between the calling connection and the called subscriber substation in the P. A. B. X. 30, including the switching link illustrated.

Supervision and release of the switching link at one of the operator positions at the switchboard in the P. A. B. X.

Continuing now with the supervision of the switching link illustrated at the first operator position 301 at the switchboard in the P. A. B. X. 30, it is pointed out that, when a connection is extended thereover to either the central office 20, the I. B. X. 40 or the distant exchange 50, both the calling connection and the called connection have supervision. In this event, when the attention of the operator at the first operator position 301 is desired by the party or operator associated with the calling connection, a control is performed over the calling connection, thereby to cause either the trunk circuit or the toll line circuit included in the calling connection to operate, whereupon ground potential is applied to the supervisory conductor engaged by the supervisory wiper 315 of the wiper carriage of the Strowger mechanism 310. This application of ground potential to the supervisory wiper 315 completes an obvious circuit, including the contacts 411 and the contacts 386 of the talk key K380, for illuminating the supervisory lamp L327. On the other hand, in this event, when the attention of the operator at the first operator position 301 is desired by the operator at the operator position included in the called connec-

tion, a control is performed over the called connection, thereby to cause either the trunk circuit or the toll line circuit included in the called connection to operate and apply ground potential to the supervisory conductor C576 extending into the first selector 500. This application of ground potential to the supervisory conductor C576 completes an obvious circuit, including the contacts 405 and 414 and the contacts 381 and 386 of the talk key K380 for illuminating the supervisory lamp L327.

The illumination of the supervisory lamp L327 indicates to the operator at the first operator position 301 that her attention is required in connection with a call routed by way of the switching link illustrated; whereupon the operator at the first operator position 301 operates the talk key K380, thereby to cause reoperation of the talk relay R370; whereupon the previously traced connection between the first operator position 301 and the switching link illustrated is recompleted.

Incident to the termination of an established connection routed by way of the switching link illustrated between a calling connection and a called connection, including the central office 20, the I. B. X. 40 or the distant exchange 50, controls are performed over the calling and called connections, thereby to complete the previously traced circuits for illuminating the supervisory lamp L327. The operator at the first operator position 301 then reestablishes the connection between the first operator position 301 and the link illustrated by operating the talk key K380. Upon discovering that both the calling and the called connections have been terminated, the operator at the first operator position 301 releases the switching apparatus, including the switching link illustrated and the toll connector 504, by momentarily operating the release call and release answer keys in the position equipment at the first operator position 301. When the release call and the release answer keys in the position equipment at the first operator position 301 are momentarily operated, ground potential is momentarily connected to both the release call conductor C382 and the release answer conductor C383 in the cable 302 extending to the first operator position 301. The application of ground potential to the release call conductor C382 in the cable 302 completes a path for short-circuiting the winding of the cut-in relay R430, this path extending from the grounded release call conductor C382 by way of the contacts 371', R430 and the contacts 437 to the grounded hold conductor C389. When the cut-in relay R430 is thus short-circuited it restores to interrupt, at the contacts 431, a further point in the previously traced path for short-circuiting the winding thereof. The application of ground potential to the release answer conductor C383 completes a path for short-circuiting the upper winding of the start relay R360, this path extending from the grounded release answer conductor C383 in the cable 302 by way of the contacts 370, C565, the upper winding of R360 and the contacts 362 and 334 to ground. When the upper winding of the start relay R360 is thus short-circuited this relay restores.

Upon restoring, the cut-in relay R430 interrupts, at the contacts 435, the previously mentioned path for applying ground potential to the hold conductor C574 extending into the first selector 500, thereby to cause the first selector 500 to be released. When the first selector 500

is released the toll connector 504 is released, in an obvious manner, and the previously mentioned circuit for energizing the winding of the toll relay R400 is interrupted, thereby to cause the latter relay to restore. Upon restoring, the start relay R360 completes, at the contacts 364, an obvious circuit, including the set of switch springs S324, for energizing the release magnet M322, thereby to cause the release magnet M322 to operate and release the wiper carriage of the Strowger mechanism 310. When the wiper carriage of the Strowger mechanism 310 is released it is returned to its normal position, whereupon the set of switch springs S325 is actuated into engagement and the set of switch springs S324 is actuated into disengagement, thereby to interrupt the previously traced circuit for energizing the release magnet M322, whereupon the release magnet M322 restores. Also, the start relay R360 interrupts, at the contacts 363, the previously traced holding circuit for energizing the intermediate winding of the cut-in relay R330, thereby to cause the latter relay to restore. Further, the start relay R360 interrupts, at the contacts 361, the previously mentioned circuit for illuminating the busy lamp L326. The extinguishment of the busy lamp L326 indicates to the operator at the first operator position 301 that the switching link illustrated is completely released.

After the operator at the first operator position 301 momentarily operates the release call and release answer keys in the position equipment at the first operator position 301 she returns the talk key K380 to its normal position, thereby to interrupt the previously traced holding circuit for energizing the lower winding of the talk relay R370, whereupon the latter relay restores. When the switching link illustrated is thus released the previously traced circuits for illuminating the supervisory lamp L327 are interrupted, thereby to cause the supervisory lamp L327 to be extinguished. At this time, the apparatus involved in the established connection is completely released and the switching link illustrated is available for further use.

In connection with the extension of a call by way of the switching link illustrated, the second selector 505 and the local connector 236 to a called subscriber substation in the P. A. B. X. 30, it is again noted that operation of the timer apparatus 510 is initiated. As previously pointed out, when the cut-in relay R430 in the finder 300 operates, ground potential is applied to the start conductor C563 extending into the timer apparatus 510. This application of ground potential to the start conductor C563 completes a circuit for energizing the upper winding of the start relay R530, this circuit extending from the grounded start conductor C563 by way of the contacts 524 and the upper winding of R530, the contacts 535, 546 and 551 and the resistor 537 to battery. When thus energized the start relay R530 operates to complete, at the contacts 534, an obvious holding circuit substantially identical to that previously traced for energizing in series the upper and lower windings thereof. Also, the start relay R530 interrupts, at the contacts 525, the previously traced original circuit for energizing the upper winding thereof, and completes, at the contacts 533, an obvious circuit, including the contacts 533, for energizing the winding of the timer relay R540. When thus energized the timer relay R540 operates to set the weighted armature thereof into

5 vibration, whereupon there is completed intermittently, at the contacts 541, an obvious circuit, including the contacts 533, for energizing the winding of the timer relay R545 in multiple with the resistor 536. It is noted that the timer relay R545 is of the slow-to-operate type; and the circuit thereof is only intermittently completed, due to the vibration of the weighted armature of the timer relay R540. Accordingly, 10 there is a considerable time delay after the operation of the timer relay R540. After the time delay mentioned the timer relay R545 operates to complete, at the contacts 548, an obvious circuit for energizing the winding of the timer relay R550 in multiple with the resistor 538. Shortly 15 after the timer relay R550 is thus energized it operates, this relay being of the slow-to-operate type. Upon operating, the timer relay R550 interrupts, at the contacts 553 the previously mentioned circuit for energizing the winding of the timer relay R540, thereby to cause the latter relay to restore. Upon restoring, the timer relay R540 interrupts, at the contacts 541, the previously traced circuit for energizing the winding of the timer relay R545, thereby to cause the latter relay to restore shortly thereafter, the winding of the timer relay R545 being short-circuited by the resistor 536. Upon restoring, the timer relay R545 interrupts, at the contacts 548, 20 the previously mentioned circuit for energizing the winding of the timer relay R550, thereby to cause the latter relay to restore shortly thereafter, the winding of the timer relay R550 being short-circuited by the resistor 538. Upon restoring, the timer relay R550 recompletes, at the contacts 553, the previously traced circuit for energizing the winding of the timer relay R540, thereby to cause the latter relay of re-operate; whereupon a new cycle of operation 25 of the timer relays R540, R545 and R550 is initiated.

40 While the timer relay R550 occupies its operated position, and when the timer relay R545 restores, it completes, at the contacts 547, a circuit for energizing the rotary magnet M518, this circuit extending from ground by way of the contacts 552, 547 and 531 and the rotary magnet M518 to battery. When thus energized the rotary magnet M518 operates, thereby to drive the wipers noted of the minor switch 511 one step in the clockwise direction. Subsequently, when the timer relay R550 restores it 45 interrupts, at the contacts 552, the previously traced circuit for energizing the rotary magnet M518, thereby to cause the rotary magnet M518 to restore. In view of the above description of the cycle of operation of the timer relays R540, R545 and R550, it will be understood that, incident to the completion of each cycle thereof, the rotary magnet M518 is operated; whereby the wipers noted of the minor switch 511 are driven 50 step by step in the clockwise direction. When the wipers noted of the minor switch 511 are driven one step in the clockwise direction the set of switch springs S515 is actuated into engagement, thereby to prepare a circuit traced hereinafter for energizing the release magnet M519.

When the subscriber at the called subscriber substation answers the call the local connector 236 operates to reverse battery over the called connection to the finder 300, thereby to cause operation of the supervisory relay R425, as previously explained. Upon operating, the supervisory relay R425 interrupts, at the contacts 427, 55 the previously traced path for applying ground

potential to the start conductor C563 extending into the timer apparatus 510 and, consequently, the previously traced holding circuit for energizing in series the upper and lower windings of the start relay R530, thereby to cause the latter relay to restore. Upon restoring, the start relay R530 interrupts, at the contacts 533, the previously traced circuit for energizing the winding of the timer relay R540, thereby to arrest the cycle of operation of the timer relays R540, R545 and R550. Also, the start relay R530 interrupts, at the contacts 531, the previously traced circuit for energizing the rotary magnet M518, thereby to arrest further operation of the minor switch 511. Finally, the start relay R530 completes, at the contacts 532, the previously mentioned circuit, including the set of switch springs S515, for energizing the release magnet M519. When thus energized the release magnet M519 operates in order to release the wipers noted of the minor switch 511, whereupon they are returned to their normal positions. When the wipers noted of the minor switch 511 are returned to their normal positions the set of switch springs S515 is actuated into disengagement, thereby to interrupt the previously traced circuit for energizing the release magnet M519 in order to cause the release magnet M519 to restore. At this time, the timer apparatus 510 is completely released.

In the event the subscriber at the called subscriber substation in the P. A. B. X. 30 does not answer the call within a predetermined time interval, the supervisory relay R425 is not operated prior to the time that the wipers noted of the minor switch 511 have been driven nine steps in the clockwise direction away from their normal positions. In this event, a circuit is completed for energizing the lower winding of the signal relay R520, this circuit extending from the grounded tenth contact engaged by the wiper 513 of the minor switch 511 by way of C563', the contacts 523 and the lower winding of R520 to battery. When thus energized the signal relay R520 operates to complete, at the contacts 522, an obvious holding circuit, including the grounded start conductor C563, for energizing the upper winding thereof. Also, the signal relay R520 interrupts, at the contacts 523, the previously traced original circuit for energizing the lower winding thereof; and interrupts, at the contacts 524, the previously traced holding circuit for energizing in series the upper and lower windings of the start relay R530, thereby to cause the start relay R530 to restore and release the minor switch 511 and to arrest operation of the timer relays R540, R545 and R550, in a manner previously explained. Finally, the signal relay R520 completes, at the contacts 521, an obvious circuit, including the interrupter conductor C560, for intermittently illuminating the hold lamp L409, ground potential being applied to the interrupter conductor C560 at a rate of approximately sixty impulses per minute.

The flashing of the hold lamp L409 indicates to the operator at the first operator position 301 that the connection has not been completed to the called subscriber substation in the P. A. B. X. 30. Accordingly, the operator at the first operator position 301 reoperates the talk key K380, thereby to cause reoperation of the talk relay R370. Upon operating, the talk relay R370 re-completes the previously traced connection between the switching link illustrated and the first operator position 301, and interrupts, at the contacts 371, the previously traced path for applying ground potential to the start conductor C563 extending into the timer apparatus 510, in order to interrupt the previously traced holding circuit for energizing the upper winding of the signal relay R520, whereupon the latter relay restores. Upon restoring, the signal relay R520 interrupts, at the contacts 521, the previously traced circuit, including the interrupter conductor C560, for intermittently illuminating the hold lamp L409, thereby to cause the hold lamp L409 to cease flashing. The operator at the first operator position 301 then advises the calling party or operator over the calling connection that the desired connection to the called subscriber substation in the P. A. B. X. 30 may not be immediately had.

Continuing now with the supervision of the switching link illustrated at the first operator position 301 at the switchboard in the P. A. B. X. 30, it is pointed out that, when a connection is extended thereover to a called subscriber substation in the P. A. B. X. 30, both the calling connection and the called connection have supervision. In this event, when the attention of the operator at the first operator position 301 is desired by the party or operator associated with the calling connection, a control is performed over the calling connection, thereby to cause the supervisory lamp L327 to be illuminated, in the manner previously explained.

Also, in this event, when the attention of the operator at the first operator position 301 is desired by the subscriber associated with the called connection, the subscriber at the called subscriber substation dials a predetermined digit. At this time, the supervisory relay R425 occupies its operated position, thereby to complete, at the contacts 426, the previously traced circuit for energizing the winding of the supervisory relay R420 in order to retain the latter relay in its operated position. When the predetermined digit mentioned is dialed the supervisory relay R425 operates and restores intermittently, thereby to complete, at the contacts 427, a circuit for energizing the winding of the supervisory relay R410, this circuit extending from ground by way of the contacts 361, 371, 401, 433, 427 and 421 and R410 to battery. When thus energized the supervisory relay R410 operates to complete, at the contacts 413, an obvious holding circuit substantially identical to that previously traced for energizing the winding thereof. Subsequently, when the supervisory relay R425 reoperates it completes, at the contacts 426, a circuit for illuminating the supervisory lamp L327, this circuit extending from ground by way of the contacts 361, 371, 401, 433, 426 and 412, the contacts 386 of the talk key K380 and the supervisory lamp L327 to battery.

When the supervisory lamp L327 is thus illuminated the operator at the first operator position 301 operates the talk key K380, thereby to cause operation of the talk relay R370, in the manner previously explained, whereupon the link illustrated is connected to the first operator position 301. Also, the talk relay R370 interrupts, at the contacts 371, the previously traced holding circuit for energizing the winding of the supervisory relay R410, thereby to cause the latter relay to restore, and interrupts, at the contacts 371, the previously traced circuit for illuminating the supervisory lamp L327.

Incident to the termination of an established connection routed by way of the switching link illustrated between a calling connection and a

called connection, including the second selector 505, the local connector 236 and a called subscriber substation in the P. A. B. X. 30, the subscriber at the called subscriber substation replaces the receiver of the telephone instrument thereat upon its associated switchhook, whereupon the local connector 236 operates to cause battery to be reversed to the finder 300, in the manner previously explained. When battery is reversed to the finder 300 the supervisory relay R425 restores, thereby to complete, at the contacts 421, the previously traced circuit for energizing the winding of the supervisory relay R410 in order to cause the latter relay to operate. Upon operating, the supervisory relay R410 completes, at the contacts 413, the previously traced holding circuit for energizing the winding thereof. Also, the supervisory relay R425 interrupts, at the contacts 426, the previously traced circuit for energizing the winding of the supervisory relay R420, thereby to cause the latter relay to restore shortly thereafter, the supervisory relay R420 being of the slow-to-release type. Upon restoring, the supervisory relay R420 completes, at the contacts 422, the previously traced path for applying ground potential to the start conductor C533 extending into the timer apparatus 516, thereby to initiate operation of the timer relays R540, R545 and R550, in the manner previously explained. When the wipers noted of the minor switch 511 are driven one step in the clockwise direction a path is completed for short-circuiting the winding of the start relay R360 at this time. The path for short-circuiting the upper winding of the start relay R360 extends from ground by way of the contacts 415, C534, the wiper 514 and engaged second contact in the associated contact bank of the minor switch 511, C535, the upper winding of R360 and the contacts 362 and 334 to ground. When the upper winding of the start relay R360 is thus short-circuited this relay restores to interrupt, at the contacts 363, the previously mentioned path for applying ground potential to the hold conductor C339, thereby to cause the cut-through relay R339 and the cut-in relay R430 to restore, in the manner previously explained. Further, the start relay R360 interrupts, at the contacts 361, the previously traced holding circuit for energizing the winding of the supervisory relay R410, thereby to cause the latter relay to restore. Incident to the restoration of the start relay R360 the finder 300 is released in the manner previously explained; and incident to the restoration of the cut-in relay R430 the first selector 500 is released, in the manner previously explained. Incident to the release of the first selector 500, the second selector 505 and the local connector 236 are released, in an obvious manner. At this time, the apparatus involved in the established connection is completely released.

The operator at the first operator position 301 may monitor an established connection completed by way of the switching link illustrated merely by operating the monitor key K440. When the monitor key K440 is thus operated there is completed, at the contacts 442 and 443 thereof, an obvious connection between the line conductors C447 and C448 in the cable 302 extending to the first operator position 301 and the line conductors C445 and C444 in the finder 300. Also, at the contacts 441 of the monitor key K440, there is completed an obvious path for applying ground potential to the monitor conductor C449 in the cable 302 extending to the first operator

position 301. This application of ground potential to the monitor conductor C449 operates the position equipment at the first operator position 301 in order to monitor the established connection routed by way of the switching link illustrated. After the operator has monitored the established connection routed by way of the switching link illustrated to her satisfaction, she returns the monitor key K440 to its normal position, thereby to interrupt the monitoring connection between the first operator position 301 and the switching link illustrated.

It is noted that the position equipment at the first operator position 301 is so connected and arranged that an established connection may be split in either direction; either end of the established connection may be rerung; either end of the established connection may be separately released; and other service functions may be performed over either end of the established connection, as particularly described in the previously mentioned Voss and Crocker patent.

In conjunction with the extension of a connection from the first operator position 301 at the switchboard, by way of the switching link illustrated, to either the central office 20, the I. B. X. 40 or the distant exchange 50, it is noted that either the first selector 500 or the selected toll connector may encounter an all-busy condition due to the presence of all-busy trunks between the first selector 500 and the group of toll connectors, due to the presence of all-busy trunks between the selected toll connector and the central office 20 or the I. B. X. 40, or due to the presence of all-busy toll lines between the selected toll connector and the distant exchange 50. In this event, either the first selector 500 or the selected toll connector operates to cause busy tone current to be returned to the finder 300 and, consequently, to the calling connection and the first operator position 301. In this event, the operator at the first operator position 301 advises the party or operator associated with the calling connection that the desired connection may not be immediately completed due to the all-busy condition.

Similarly, in conjunction with the extension of a connection from the first operator position 301 at the switchboard, by way of the switching link illustrated, to a called subscriber substation in the P. A. B. X. 30, it is noted that either the first selector 500 or the selected second selector may encounter an all-busy condition, due to the presence of all-busy trunks between the first selector 500 and the group of second selectors or due to the presence of all-busy trunks between the selected second selector and the group of local connectors. Further, the selected local connector may test the selected telephone line extending to the called subscriber substation in the P. A. B. X. 30 as busy. In this event, either the first selector 500, the selected second selector or the selected local connector operates to cause busy tone current to be returned to the finder 300 and, consequently, to the calling connection. However, in this event, the busy tone current is not returned to the first operator position 301, as the operator has previously returned the talk key K380 to its normal position after all of the digits were registered in the register sender apparatus in the position equipment associated with the first operator position 301. More particularly, busy tone current is returned over the line conductor C572 which is connected by way of the previously traced path, including the call-

ing connection to the line conductor C571. Also, this busy tone current is impressed upon the tone conductor C562 which is connected by way of the contacts 431 to the line conductor C571.

Considering now the operation of the tone apparatus 600, it is noted that, when the first operator position 301 at the switchboard is occupied, ground potential is applied to the start conductor C632, thereby to complete an obvious circuit for energizing the winding of the switch relay R630 in the tone apparatus 600. When thus energized the switch relay R630 operates to complete, at the contacts 631, an obvious circuit for energizing the primary winding 651 of the power supply transformer 650, the line conductors C655 and C656 being connected to a suitable source of A. C. supply. When the primary winding 651 of the power supply transformer 650 is thus energized an obvious circuit, including the secondary winding 652 thereof, is completed for heating the filamentary cathode 671 of the rectifier tube 670. Also, an obvious circuit, including the secondary winding 654 of the power supply transformer 650, is completed for heating the filamentary cathode 678 of the control tube 675. Finally, an obvious circuit, including the secondary winding 654 of the power supply transformer 650, is completed for energizing the cathode heater 685 of the amplifier tube 680.

The rectifier tube 670 operates as a full wave rectifier and functions to deliver direct current to the winding of the tone relay R615, the operating circuit for this relay extending from ground by way of the secondary winding 653 of the power supply transformer 650, the anodes 672 and 673 and the cathode 671 of the rectifier tube 670, the choke coil 640, the resistor 641, R615, the anode 676 and the cathode 678 of the control tube 675 and the secondary winding 654 of the power supply transformer 650 to ground. At this point, it is noted that the grid 677 of the control tube 675 is connected to ground through the resistor 636 and accordingly is unbiased. Hence, a substantial anode current traverses the space current path of the control tube 675 and the winding of the tone relay R615. The control electrode 683 of the amplifier tube 680 is also at ground potential and hence a substantial anode current normally traverses the space current path of this tube. When the winding of the tone relay R615 is thus energized this relay operates to interrupt, at the contacts 616, a point in a circuit traced hereinafter for applying ground potential to the control conductor C566. This condition of the tone apparatus 600 is maintained at this time in order to retain the tone relay R615 operated.

As previously explained, incident to the operation of the cut-in relay R430 in the finder 300, operation of the timer apparatus 510 is initiated. When the wipers noted of the minor switch 511 are driven one step in the clockwise direction, a circuit is completed at the wiper 513 and engaged second contact in the associated contact bank thereof for energizing the winding of the start relay R610 in the tone apparatus 600. This circuit extends from ground by way of R610, the control conductor C566, the wiper 513 and engaged second contact in the associated contact bank of the minor switch 511 and C563 to the contacts 523, from the contacts 523 by way of the lower winding of R520 to battery, and from the contacts 523 by way of the resistor 539 to battery. When this series circuit

is completed the start relay R610 operates. However, the signal relay R520 does not operate, the latter relay being of the marginal type. Upon operating, the start relay R610 prepares, at the contacts 612, a circuit traced hereinafter for energizing the winding of the control relay R625; interrupts, at the contacts 614, an obvious normal path for connecting one terminal of the condenser 674 to ground; prepares, at the contacts 611, a circuit traced hereinafter for energizing the winding of the control relay R620; and completes, at the contacts 613, a connection between the primary windings 661 and 662 of the coupling transformer 660 and the tone conductor C562. This connection extends from the tone conductor C562 by way of the wiper 512 and engaged second contact in the associated contact bank of the minor switch 511, C567, the condenser 674, the contacts 613 and the parallel connected primary windings 661 and 662 of the coupling transformer 660 to ground.

At this time, in the event no busy tone voltage is impressed upon the tone conductor C562, no further operation of the tone apparatus 600 is effected; and when the wipers noted of the minor switch 511 are driven an additional step in the clockwise direction the previously traced circuit for energizing the winding of the start relay R610 is interrupted, thereby to cause the latter relay to restore. Upon restoring, the start relay R610 interrupts, at the contacts 613, the previously traced connection between the tone conductor C562 and the primary windings 661 and 662 of the coupling transformer 660. On the other hand, in the event busy tone voltage is impressed upon the tone conductor C562, the primary windings 661 and 662 of the coupling transformer 660 are energized, whereby a control voltage is induced in the series connected secondary windings 663 and 664 thereof which is impressed upon the control grid 683 of the amplifier tube 680. This voltage impressed between the grid 683 and the cathode 684 of the amplifier tube 680 is amplified through this tube and is impressed upon the control electrode 677 of the control tube 675 through the coupling condenser 635. This voltage is in the form of a distorted flat top wave with the reference axis so disposed that the larger wave loops are impressed negatively upon the control electrode 677 of the control tube 675. When the control tube 675 is thus negatively biased, the average value of the space current traversing this tube and the winding of the tone relay R615 is decreased below the value required to hold the tone relay R615 operated. Accordingly, the tone relay R615 restores after a time interval to complete, at the contacts 616, the previously mentioned circuit for energizing the winding of the control relay R625, this circuit extending from ground by way of the contacts 616, 612, 622 and R625 to battery. When thus energized the control relay R625 operates to complete, at the contacts 626, a path for short-circuiting the winding of the control relay R620, this path extending from ground by way of the contacts 616, 612, 622 and 626, R620 and the contacts 611 to ground.

The busy tone voltage impressed upon the tone conductor C562 is intermittent. Accordingly, when the first mentioned splash of busy tone impressed upon the tone conductor C562 subsides, the primary windings 661 and 662 of the coupling transformer 660 are deenergized, whereby the current traversing the space current path of the control tube 675 and the winding of the tone

relay R615 is increased to normal to cause the reoperation of this relay.

Upon reoperating, the tone relay R615 interrupts, at the contacts 616, the previously traced original circuit for energizing the winding of the control relay R625 and the previously traced path for short-circuiting the winding of the control relay R620; whereupon a series circuit is completed for energizing the windings of the control relays R620 and R625. This series circuit extends from ground by way of the contacts 611, R620, the contacts 626 and R625 to battery. Shortly after this series circuit is completed the control relay R620 operates, this relay being of the slow-to-operate type. Upon operating, the control relay R620 prepares, at the contacts 621, a path traced hereinafter for applying ground potential to the control conductor C566 and for short-circuiting the winding of the start relay R610.

When the next splash of busy tone voltage is applied to the tone conductor C562 the previously traced circuit for energizing the primary windings 661 and 662 of the coupling transformer 660 is recompleted, thereby to cause the release of the tone relay R615, in the manner explained above. Upon restoring, the tone relay R615 completes, at the contacts 616, the previously mentioned path for applying ground potential to the control conductor C566 and for short-circuiting the winding of the start relay R610. This path extends from ground by way of the contacts 616, 612 and 621 to the control conductor C566, and from the control conductor C566 by way of R610 to ground. Accordingly, a direct ground potential is momentarily applied to the control conductor C566 and the winding of the start relay R610 is short-circuited, thereby to cause the latter relay to restore. Upon restoring, the start relay R610 interrupts, at the contacts 611, the previously traced holding circuit for energizing in series the windings of the control relays R620 and R625, thereby to cause the latter relays to restore. Also, upon restoring, the start relay R610 interrupts, at the contacts 612, the previously traced path for applying direct ground potential to the control conductor C566, and interrupts, at the contacts 613, the previously traced circuit for energizing the primary windings 661 and 662 of the coupling transformer 660. Finally, the start relay R610 completes, at the contacts 614, the previously mentioned path for connecting direct ground potential to one terminal of the condenser 674, thereby to discharge this condenser.

The application of direct ground potential to the control conductor C566 in the tone apparatus 600 completes a direct ground potential circuit for energizing the lower winding of the signal relay R520, this circuit extending from the grounded control conductor C566 by way of the wiper 513 and engaged second contact in the associated contact bank, C563', the contacts 523 and the lower winding of R520 to battery. When thus energized, the signal relay R520 operates to complete, at the contacts 522, the previously traced holding circuit for energizing the upper winding thereof, and interrupts, at the contacts 524, the previously traced holding circuit for energizing in series the upper and lower windings of the start relay R530, thereby to cause the latter relay to restore in order to arrest further operation of the timer relays R540, R545 and R550. Finally, the signal relay R520 completes,

at the contacts 521, the previously traced circuit for flashing the hold lamp L409.

The flashing of the hold lamp L409 indicates to the operator at the first operator position 301 that the connection to the called subscriber substation in the P. A. B. X. 30 has not been completed, whereupon the operator at the first operator position 301 operates the talk key K380, thereby to cause operation of the talk relay R370. Upon operating, the talk relay R370 reconnects the switching link illustrated to the first operator position 301 and interrupts, at the contacts 371, the previously traced holding circuit for energizing the upper winding of the signal relay R520, thereby to cause the latter relay to restore. Upon restoring, the signal relay R520 interrupts, at the contacts 521, the previously traced circuit for flashing the hold lamp L409. The operator at the first operator position 301 then advises the party or operator associated with the calling connection that the desired connection may not immediately be had due to the all-busy condition.

At this point, it is noted that the operation of the tone apparatus 600, described above, is effected only in the event the complete operation thereof is obtained within a very short time interval and while the wipers noted of the minor switch 511 in the timer apparatus 510 engage the second contacts in the associated contact banks. Accordingly, the tone apparatus 600 is operative, in the manner described above, in the event busy tone potential is impressed upon the tone conductor C562, as busy tone current comprises a series of very rapid splashes. Accordingly, it will be understood that other tones occurring at considerably spaced-apart time intervals and impressed upon the tone conductor C562 will not cause the above-described operation of the tone apparatus 600 in view of the fact that the second splash of tone will occur after the wipers noted of the minor switch 511 disengage the second contacts in the associated contact banks. For example, this condition prevails when ring-back tone current is impressed upon the tone conductor C562.

Again considering the operation of the tone apparatus 600, it is noted that the operation of this apparatus is effective to cause operation of the signal relay R520 only in the event the tone relay R615 restores twice, while the wipers noted of the minor switch 511 engage the second contacts in the associated contact bank; which condition prevails only in the event busy tone current is impressed upon the tone conductor C562, as busy tone current is impressed upon the conductor C562 in the form of rapid splashes, as previously noted.

At this point, it is noted that, when the local connector 236 operates to seize the telephone line extending to the called subscriber substation and causes ringing current to be projected thereover and ring-back tone current to be returned over the previously traced connection to the finder 300, this ring-back tone current is impressed upon the tone conductor C562. However, the ring-back tone current impressed upon the tone conductor C562 comprises splashes spaced apart by a considerable time interval; accordingly, complete operation of the tone apparatus 600 does not occur for the reasons previously noted.

Extension of delayed calls from the switchboard in the P. A. B. X.

The operator at each operator position at the switchboard in the P. A. B. X. 30 may set up a

delayed call by utilizing any one of the switching links in the associated group. For example, the operator at the first operator position 301 may set up a delayed call by utilizing the switching link illustrated in the associated group by first operating the talk key K380 and then the delayed call key in the position equipment at the first operator position 301. When the talk key K380 is operated the talk relay R370 operates, thereby to connect the switching link illustrated to the first operator position 301. When the delayed call key in the position equipment at the first operator position 301 is then operated the switching link illustrated is marked against selection to the distributor 250; ground potential is applied to the delayed call conductor C244; and operation of the finder 300 is initiated. The application of ground potential to the delayed call conductor C244 causes the vertical movement of the wiper carriage of the Strowger mechanism 310 to be arrested in the first vertical level; whereupon the wiper carriage of the Strowger mechanism 310 is driven in the rotary direction step by step until a trunk extending to an idle delayed call selector in the associated group, such as the trunk 509 extending to the delayed call selector 570, is seized thereby. After the finder 300 operates to seize the trunk 509 extending to the delayed call selector 570, this delayed call selector is rendered responsive to digits dialed thereto. The operator at the first operator position 301 then proceeds to operate the calling device in the associated position equipment in order to cause digits to be transmitted by way of the finder 300 and the trunk 509 to the delayed call selector 570. The delayed call selector 570 operates in response to the digits transmitted thereto, whereby a connection is set up over the associated toll switch train to either the central office 20, the I. B. X. 40 or the distant exchange 50; or a connection is set up over the associated toll switch train and the local switch train in the P. A. B. X. 30 to a subscriber substation in the P. A. B. X. 30. After this connection has been set up the operator at the first operator position 301 returns the delayed call key in the position equipment thereat to its normal position, whereupon the apparatus is in readiness to extend a call from the first operator position 301 by way of the first selector 500, in the manner previously explained.

The supervision and the release of a delayed call routed by way of the switching link illustrated at the first operator position 301 are the same as previously described.

Local calls in the P. A. B. X. and in the I. B. X.

Local calls in the P. A. B. X. 30 are completed and released between the automatic subscriber substations therein by way of the local switch train in the P. A. B. X. 30 and entirely under the control of the subscribers at the subscriber substations, in accordance with conventional practice, the local finder-selector links and the local connectors being utilized.

Also, local calls in the I. B. X. 40 are completed and released between the automatic subscriber substations therein by way of the switch train in the I. B. X. 40 and entirely under the control of the subscribers at the subscriber substations, in accordance with conventional practice, the finder-connector links being utilized. Further calls in the I. B. X. 40 between the subscriber substations and the operator position 217 are

completed in either direction by way of the switch train therein in accordance with conventional practice, the finder-connector links being utilized.

Conclusions

From the foregoing, it is apparent that a telephone system is provided, which comprises an exchange, including an automatic switchboard provided with a number of operator positions, switching apparatus selectively operative under the control of the operators at the operator positions for performing the various toll and trunk services in an efficient manner, and an improved arrangement for supervising at the operator positions at the switchboard the operations of the switching apparatus.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, a plurality of lines, an operator position, a link, means selectively controllable from said operator position for connecting said link to and for disconnecting said link from said operator position, means for connecting said link to a calling one of said lines, means for connecting said link to a called one of said lines, means responsive to the connection of said link to a busy called line for impressing a busy signal upon said link, whereby said busy signal impressed upon said link is transmitted to the calling line connected to said link and also to said operator position in the event said link is connected to said operator position, a signal device associated with said operator position, and means responsive to the presence of said busy signal upon said link and governed only in the event said link is disconnected from said operator position for controlling said signal device.

2. In a telephone system, a plurality of lines, an operator position, a link, means selectively controllable from said operator position for connecting said link to and for disconnecting said link from said operator position, means for connecting said link to a calling one of said lines, means for connecting said link to a called one of said lines, means responsive to the connection of said link to a busy called line for impressing a busy signal upon said link, whereby said busy signal impressed upon said link is transmitted to the calling line connected to said link and also to said operator position in the event said link is connected to said operator position, a signal device associated with said operator position, busy apparatus operative to control said signal device, an operating circuit for said busy apparatus, means responsive to the disconnection of said link from said operator position for preparing said operating circuit, and additional means responsive to the presence of said busy signal upon said link for preparing said operating circuit, whereby said operating circuit is completed only in the event it has been previously prepared.

3. In a telephone system, a plurality of lines, an operator position, a link including an answer switch and a call switch, means selectively controllable from said operator position for connecting said link to and for disconnecting said link from said operator position, means controlled when said link is connected to said oper-

ator position for operating said answer switch to connect a calling one of said lines to said link, thereby to extend the call on the calling line to said operator position to be answered, means controllable from said operator position when said link is connected thereto for initiating operation of said call switch to connect a called one of said lines to said link, whereby the complete operation of said call switch to connect a called line to said link may occur either while said link is connected to said operator position or after said link has been disconnected from said operator position, means responsive to the connection of said link to a busy called line for impressing a busy signal upon said link, whereby said busy signal impressed upon said link is transmitted to the calling line connected to said link and also to said operator position in the event said link is connected to said operator position, a signal device associated with said operator position, and means responsive to the presence of said busy signal upon said link and governed only in the event said link is disconnected from said operator position for controlling said signal device.

4. In a telephone system, a plurality of lines, an operator position, a link, means selectively controllable from said operator position for connecting said link to and for disconnecting said link from said operator position, means for connecting said link to a calling one of said lines, means for connecting said link to a called one of said lines, means responsive to the connection of said link to a busy called line for impressing a busy signal upon said link, whereby said busy signal impressed upon said link is transmitted to the calling line connected to said link and also to said operator position in the event said link is connected to said operator position, a signal device associated with said operator position, an electric discharge device including a space current path, means controlled in accordance with the resistance of said space current path for controlling said signal device, and means responsive to the presence of said busy signal upon said link and governed only when said link is disconnected from said operator position for controlling the resistance of said space current path.

5. In a telephone system, a plurality of lines, an operator position, a link, means selectively controllable from said operator position for connecting said link to and for disconnecting said link from said operator position, means for connecting said link to a calling one of said lines, means for connecting said link to a called one of said lines, means responsive to the connection of said link to a called line for impressing either a first signal or a second signal upon said link depending upon the idle or busy condition of the called line, whereby the signal impressed upon said link is transmitted to the calling line connected to said link and also to said operator position in the event said link is connected to said operator position, a signal device associated with said operator position, and means operative in response to the presence of only a predetermined one of said signals upon said link and governed only in the event said link is disconnected from said operator position for controlling said signal device.

6. In a telephone system, a plurality of lines, an operator position, a link, means selectively controllable from said operator positions for connecting said link to and for disconnecting said

link from said operator position, means for connecting said link to a calling one of said lines, means for connecting said link to a called one of said lines, means responsive to the connection of said link to a called line for impressing either a first signal or a second signal upon said link depending upon the idle or busy condition of the called line, whereby the signal impressed upon said link is transmitted to the calling line connected to said link and also to said operator position in the event said link is connected to said operator position, a timer, means responsive to the connection of said link to a called line and governed only in the event said link is disconnected from said operator position for operating said timer, a signal device associated with said operator position, apparatus operative through a complete cycle to control said signal device, means governed jointly by the presence of either one of said signals upon said link and the operation of said timer for initiating operation of said apparatus, and means governed by the operation of said timer for arresting operation of said apparatus, whereby said apparatus is operated through a complete cycle of operation only in the event a predetermined one of said signals is impressed upon said link.

7. In a telephone system, a plurality of lines, an operator position, a link, means selectively controllable from said operator position for connecting said link to and for disconnecting said link from said operator position, means for connecting said link to a calling one of said lines, means for connecting said link to a called one of said lines, means responsive to the connection of said link to a busy called line for impressing a busy signal upon said link, whereby said busy signal impressed upon said link is transmitted to the calling line connected to said link and also to said operator position in the event said link is connected to said operator position, a signal device associated with said operator position, means responsive to the presence of said busy signal upon said link and governed only in the event said link is disconnected from said operator position for controlling said signal device, and additional means responsive to the connection of said link to an idle called line and governed only in the event the call on the idle called line is not answered within a predetermined time interval after said link is connected thereto and only in the event said link is disconnected from said operator position for controlling said signal device.

8. In a telephone system, a plurality of lines of different classes, an operator position, a link, means selectively controllable from said operator positions for connecting said link to and for disconnecting said link from said operator position, means for connecting said link to a calling one of said lines, means for connecting said link to a called one of said lines, means responsive to the connection of said link to a busy called line for impressing a busy signal upon said link, whereby said busy signal impressed upon said link is transmitted to the calling line connected to said link and also to said operator position in the event said link is connected to said operator position, a signal device associated with said operator position, normally effective means responsive to the presence of said busy signal upon said link and governed only in the event said link is disconnected from said operator position for controlling said signal device, and means controlled when said link is connected to a called line of a

predetermined class for rendering ineffective said last-mentioned means.

9. In a telephone system, an operator position, a switching link operative to extend connections from said operator position, means controllable from said operator position for selectively operating said switching link, means responsive to the encounter of a predetermined condition by said switching link for impressing a signal thereupon, a signal device associated with said operator position, an electric discharge device including a space current path, means controlled in accordance with the current traversing said space current path for controlling said signal device, and means responsive to the presence of said signal upon said switching link for controlling the current traversing said space current path.

10. In a telephone system, an operator position, a switching link operative to extend connections from said operator position, means controllable from said operator position for selectively operating said switching link, means responsive to the encounter of a predetermined condition by said switching link for impressing a signal thereupon, a signal device associated with said operator position, an electric discharge device including a space current path and a control electrode, means controlled in accordance with the current traversing said space current path for controlling said signal device, and means for amplifying said signal impressed upon said switching link and for impressing said amplified signal upon said control electrode, thereby to control the current traversing said space current path.

11. In a telephone system, an operator position, a link including a voice current channel, means controllable from said operator position for extending a connection by way of said link, means controlled when a predetermined connection is extended by way of said link for impressing a signal by way of a high impedance path upon said channel, a signal device associated with said operator position, an electric discharge device including a space current path, means controlled in accordance with the current traversing said space current path for controlling said signal device, and means responsive to the presence of said signal upon said channel for controlling the current traversing said space current path.

12. In a telephone system, a plurality of lines, an operator position, a link, means controllable from said operator position for connecting said link to a called one of said lines, means responsive to the connection of said link to a called line having a predetermined condition thereon for impressing a signal upon said link, a signal device associated with said operator position, an electric discharge device including a space current path, means controlled in accordance with the resistance of said space current path for controlling said signal device, and means responsive to the presence of said signal upon said link for controlling the resistance of said space current path.

13. In a telephone system, a plurality of lines, an operator position, a link, means controllable from said operator position for connecting said link to a called one of said lines, means responsive to the connection of said link to an idle called line for impressing a first signal upon said link, means responsive to the connection of said link to a busy called line for impressing a second signal upon said link, a signal device associated

with said operator position, an electric discharge device including a space current path, means controlled in accordance with the resistance of said space current path for controlling said signal device, and means nonresponsive to the presence of said first signal upon said link and responsive to the presence of said second signal upon said link for controlling the resistance of said space current path.

10 14. In a telephone system, a plurality of lines, a plurality of automatic switches having access to said lines, a switching link having access to said switches, an operator position, means controllable from said operator position for operating said switching link to select an idle one of said switches and then for operating a selected one of said switches to select one of said lines, means responsive to the operation of said switching link when all of said switches are busy for impressing a signal upon said switching link, additional means responsive to selection by a selected one of said switches of a busy one of said lines for impressing said signal upon said switching link, a signal device associated with said operator position, an electric discharge device including a space current path, means controlled in accordance with the resistance of said space current path for controlling said signal device, and means responsive to the presence of said signal upon said switching link for controlling the resistance of said space current path.

15 15. In a telephone system, a plurality of lines, an operator position, a link, means controllable from said operator position for connecting said link to a called one of said lines, means responsive to the connection of said link to a busy called line for impressing a signal upon said link, a visual signal device associated with said operator position, an electric discharge device including a space current path, means responsive to a predetermined change in the resistance of said space current path for operating said signal device, and means responsive to the presence of said signal upon said link for effecting said predetermined change in the resistance of said space current path.

16 16. In a telephone system, a plurality of lines of different classes, an operator position, a link, means controllable from said operator position for connecting said link to a called one of said lines, means responsive to the connection of said link to a busy called line for impressing a signal upon said link, a signal device associated with said operator position, an electric discharge device including a space current path, means controlled in accordance with the resistance of said space current path for controlling said signal device, normally effective means responsive to the presence of said signal upon said link for controlling the resistance of said space current path, and means controlled when said link is connected to a called line of a predetermined class for rendering ineffective said last-mentioned means.

17 17. In a telephone system, a plurality of lines, an operator position, a link, means controllable from said operator position for connecting said link to a called one of said lines, a signal device associated with said operator position, means responsive to the connection of said link to a busy called line for controlling said signal device, and additional means responsive to the connection of said link to an idle called line and governed only in the event the call on the idle called line is not answered within a predetermined time in-

terval after said link is connected thereto for controlling said signal device.

18. In a telephone system, a plurality of lines, an operator position, a link, means controllable from said operator position for connecting said link to a called one of said lines, a signal device associated with said operator position, means responsive to the connection of said link to a busy called line for controlling said signal device, a timer, means responsive to the connection of said link to an idle called line for initiating operation of said timer, means responsive to the answering of the call on the idle called line for arresting operation of said timer, and additional means responsive to a predetermined operation of said timer for controlling said signal device.

19. In a telephone system, a plurality of lines, an operator position, a link, means controllable from said operator position for connecting said link to a called one of said lines, a visual signal device associated with said operator position, means responsive to the connection of said link to a busy called line for operating said signal device, and additional means responsive to the connection of said link to an idle called line and governed only in the event the call on the idle called line is not answered within a predetermined time interval after said link is connected thereto for operating said signal device.

20. In a telephone system, a plurality of lines of different classes, an operator position, a link, means controllable from said operator position for connecting said link to a called one of said lines, a signal device associated with said operator position, normally effective means responsive to the connection of said link to a busy called line for controlling said signal device, additional normally effective means responsive to the connection of said link to an idle called line and governed only in the event the call on the idle called line is not answered within a predetermined time interval after said link is connected thereto for controlling said signal device, and means controlled when said link is connected to a called line of a predetermined class for rendering ineffective both of said last two mentioned means.

21. In a telephone system, a plurality of lines, an operator position, a link, means controllable from said operator position for connecting said link to a called one of said lines, a timer, means responsive to the connection of said link to a called line for operating said timer and for impressing either a first signal or a second signal upon said link depending upon the idle or busy condition of the called line, a signal device associated with said operator position, apparatus operative through a complete cycle to control said signal device, means governed jointly by the presence of either one of said signals upon said link and the operation of said timer for initiating operation of said apparatus, and means governed by the operation of said timer for arresting operation of said apparatus, whereby said apparatus is operated through a complete cycle of operation only in the event a predetermined one of said signals is impressed upon said link.

22. In a telephone system, a plurality of lines, an operator position, a link, means controllable

from said operator position for connecting said link to a called one of said lines, a timer, first and second intermittent signal voltages having different periodicities, means responsive to the connection of said link to a called line for operating said timer and for impressing either said first signal voltage or said second signal voltage upon said link depending upon the idle or busy condition of the called line, a signal device associated with said operator position, apparatus operative through a complete cycle to control said signal device, means governed jointly by the presence of either one of said signal voltages upon said link and the operation of said timer for initiating operation of said apparatus, and means governed by the operation of said timer for arresting operation of said apparatus, whereby said apparatus is operated through a complete cycle of operation only in the event a predetermined one of said signal voltages is impressed upon said link.

23. In a telephone system, a plurality of lines, an operator position, a link, means controllable from said operator position for connecting said link to a called one of said lines, a timer, means responsive to the connection of said link to a called line for operating said timer and for impressing either a first signal or a second signal upon said link depending upon the idle or busy condition of the called line, a visual signal device associated with said operator position, apparatus operative through a complete cycle to operate said signal device, means governed jointly by the presence of either one of said signals upon said link and the operation of said timer for initiating operation of said apparatus, and means governed by the operation of said timer for arresting operation of said apparatus, whereby said apparatus is operated through a complete cycle of operation only in the event a predetermined one of said signals is impressed upon said link.

24. In a telephone system, a plurality of lines of different classes, an operator position, a link, means controllable from said operator position for connecting said link to a called one of said lines, a timer, normally effective means responsive to the connection of said link to a called line for operating said timer, means controlled when said link is connected to a called line of a predetermined class for rendering ineffective said last-mentioned means, means responsive to the connection of said link to a called line for impressing either a first signal or a second signal upon said link depending upon the idle or busy condition of the called line, a signal device associated with said operator position, apparatus operative through a complete cycle to control said signal device, means governed jointly by the presence of either one of said signals upon said link and the operation of said timer for initiating operation of said apparatus, and means governed by the operation of said timer for arresting operation of said apparatus, whereby said apparatus is operated through a complete cycle of operation only in the event a predetermined one of said signals is impressed upon said link.

THOMAS F. CROCKER.
